UNITED STATES PATENT OFFICE.

WARREN W. CARPENTER, OF QUEENS, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed April 1, 1924, Serial No. 703,362. Renewed April 5, 1928.

This invention relates to telephone exchange systems and more especially it has to do with telephone systems of the class wherein automatic switching apparatus is employed either entirely or in part for the establishment of conversational connections.

In systems where recording senders are located at the central office for receiving records from calling subscribers' lines or from operators' positions to, in turn, exercise a control over the operation of a series of selective switches, it is found that the efficiency and speed of operation may be enhanced by providing a number of controlling mechanisms or markers also situated at the central office and separate from the recording senders. A part of the duties ordinarily performed by the senders are delegated to these markers, which receive a portion of the record from the senders to which they are connected and thereupon govern the selective operation of one or more of the switches. Other markers are subsequently associated with the senders and in their turn govern succeeding switches to further extend the connection. By providing a plurality of these controlling markers each equivalent in function to all others and common to all of the recording senders and arranging the former to be associated with any of a large number of selective switches which they control, and since the holding time of a marker is extremely short due to the limited functions it has to perform, and by working the markers simultaneously, the result achieved is that the number of calls that may be handled in a given unit of time by a given number of selective switches is materially increased.

Accordingly, it is the principal object of this invention to increase the speed and general efficiency of automatic telephone systems through an improved organization in the recording and switch controlling equipment.

A feature of the invention relates to the provision, in a system having selective switches, and a number of recording senders, of a number of equivalent controlling markers, each associable with any sender and with any switch, and so arranged that a plurality of said markers may be connected simultaneously to respective senders and respective switches for controlling the extension of a number of calls simultaneously.

Another feature relates to the provision of means whereby each of the markers may be connected to each of a plurality of switches in succession for selectively operating such switches.

Another feature consists in a connector switch for connecting the senders to the markers, wherein each sender normally prefers a different one of the markers and the arrangement is such that any sender may have access to any of the markers as a later choice in case its preferred choice marker is engaged together with means for connecting simultaneously a plurality of senders to respective markers.

A further feature of the invention relates to the provision, in a system where a number of markers are employed for determining the operation of switches in completing calls to called lines, of a plurality of control devices or translators each serving exclusively a portion of the total number of called lines, together with means for connecting said markers to the proper one of the translators.

A still further feature relates to a novel testing plan wherein a three-point test is made to ascertain an idle link on the incoming selector which can reach an idle trunk leading to the connector, which idle trunk, in turn, has access to an idle link in the connector switch.

According to the last feature a group of trunks leading from an incoming selector switch is distributed among two vertical rows of contacts in the connector. On this account, each horizontal link in the connector has access to two trunks of the group, one in each vertical row. Accordingly, it is necessary to render both the incoming trunks non-selectable in case the corresponding link at the connector is busy. The testing operations take place in the marker.

Another feature relates to an arrangement for sending a class-of-service record from any one of the markers through the frame connector which attaches said marker to the selector switch, to the trunk incoming to said selector switch for certain classes of calls.

A still further feature consists in a plan for effectively enlarging groups of trunks by dividing a single group among a number of selectors and providing means whereby the frame connector gives the marker the

necessary information to enable it to make connection to the proper subdivision of the total group of trunks.

5 A further feature relates to a releasing arrangement whereby the normal release of the marker is made to depend upon the fact that the selective switch which it has controlled has properly operated.

10 According to this feature, a test circuit is provided including contacts of the switch, the closure of which gives the marker a signal that the switch has operated and that the marker may release forthwith.

15 The drawing, which is partly diagrammatic and partly in full detail, illustrates the circuits and apparatus in a local telephone office. The equipment shown is capable of receiving calls from subscribers' lines which terminate as calling lines in the local 20 office and of completing these calls to any of the subscribers' lines which terminate as called lines in the same office. Moreover, it is designed to complete calls to the various types of operators' positions as customarily 25 employed in commercial exchanges. Furthermore, the equipment and apparatus shown in this disclosure is designed to extend calls from the local office over outgoing trunks to the various types of outlying offices 30 with which connection may be desired. Again, it is prepared to receive calls incoming from outlying offices and to complete them to local subscribers' lines. For the purpose of this case, however, it has been considered sufficient to confine the description to 35 local office working and to a point out only in a general way the manner in which interoffice connections are effected.

40 Referring to the drawing Figs. 1 to 40 when taken in the order illustrated in Fig. 44, disclose circuits and apparatus employed in the establishment of connections between calling and called lines.

45 Fig. 1 shows two calling subscribers' lines together with a portion of the control circuits of the line switch.

50 Fig. 2 illustrates diagrammatically a coordinate line switch in which the calling lines appear.

55 Fig. 3 shows one of the trunk circuits leading from the line switch.

Fig. 4 illustrates a portion of a coordinate district selector switch in which terminate the trunks leading from the line switches.

55 Fig. 5 shows two of the trunk circuits outgoing from the district selector, shown in Fig. 4.

60 Fig. 6 shows one of the coordinate office selector switches in which terminate the trunks leading from the district selectors and the trunks from which lead to the distant offices.

65 Fig. 7 shows control circuits associated with one of the trunks leading from the district selector switch.

Fig. 8 illustrates a portion of a coordinate incoming selector switch in which terminate trunks from the district switches.

Fig. 9 illustrates a number of trunks leading from the incoming selector switches to the final connectors.

Figs. 10 and 11 taken together, illustrate a portion of one of the final connector switches which have access to the called subscribers' lines and to private branch exchange trunks. 75

Fig. 12 shows a coordinate sender selector switch for associating the trunks with the register senders.

Fig. 13 shows control circuits for the sender selector. 80

Fig. 35 shows the time controlling mechanism.

5 Fig. 36 shows the incoming marker translator.

Fig. 37 illustrates the incoming frame connectors, for connecting the incoming markers to the incoming switches.

10 Fig. 38 shows the connecting device for associating the incoming marker with one of a number of final translators.

Fig. 39 shows the connecting device for associating the incoming markers with the 15 groups of trunks leading from the incoming to the connector switches.

Fig. 40 shows a portion of one of the final translators and also a connecting device for associating the same with final or connector 20 switches.

Figs. 41 and 42 taken together comprise a diagram showing the relative disposition of the various parts of the complete system.

Fig. 43 is a schematic illustration of the 25 manner in which the trunks are arranged between the incoming and final switches.

Fig. 44 is a chart showing the manner in which the several sheets of drawings should be arranged.

30 *General description of the system and apparatus.*

Referring first to Figs. 41 and 42, descriptions will be given of the general plan of the 35 system. The lines 4100 enter the office and terminate in a number of line switches, such as switch 4101. Outgoing from these switches are a number of trunks which extend to district selectors. For reasons which 40 will appear hereinafter, the district selector switches are divided into a number of groups, two of which groups, 4106 and 4107 are illustrated. The group 4106 comprises a number of district selector frames, 45 two of which, 4108 and 4109 are shown, and trunks such as the trunks 4104 and 4105 leading from the line switches are distributed among these district selectors. In like manner, other trunks 4102 and 4103 50 extend to the district selectors 4110 and 4111 of the second group 4107. Other groups may be provided.

The trunks outgoing from the district selector switches lead in different directions. 55 For example, some of the trunks 4123 and 4125 extend to office selector switches. The office selectors may be arranged in groups similar to the district switches, the selector 4127 being of one group, and the selector 4128 being of a second group of office selectors. The trunks 4132 leading from the office selectors extend to distant offices to take care of the interoffice traffic.

60 Other trunks leading from the district selector switches, such as the trunks 4122 and

4124 extend to incoming switches located in the same central office.

These incoming switches are divided into two groups, group 4200 comprising the switches 4202 and 4203 and group 4201 comprising the switches 4204 and 4205. The trunks outgoing from the incoming switches, such as trunks 4212 and 4213 lead to the various connector switches of the several groups. Only one group of connector 75 switches 4214, which includes the switches 4215 and 4216 is illustrated in the drawing. The connector switches have access to the called lines as 4217 and 4218.

The trunks which lead from the line 80 switch to the district selectors also appear in the sender selector switches 4112 which operate to extend these trunks to the register senders. Two of these senders 4113 and 4114 are shown. The sender connector comprises a plurality of sections 4115, 4116, etc., which serve to connect the senders to the outgoing markers 4117 and 4118. While only two of the markers are illustrated, any suitable number may be provided.

85 In order to connect the markers to the district frames, there are provided a number of frame connectors, one for each group of district selector frames. Frame connector 4119, for instance, serves to connect any of the markers to any of the frames in the selector group 4106. Likewise the frame connector 4120 serves to connect any of the markers to any of the frames in the district selector group 4107.

90 The outgoing markers are connected to the trunks outgoing from the district switches by means of trunk connectors 4121, 4133, etc.

In a similar manner frame connectors 4129 and 4130 are provided for associating the 95 outgoing markers respectively with the office selector switches of the two corresponding groups, while trunk connectors such as the trunk connector 4131 are provided for associating the outgoing markers with the groups of trunks leading from the office switches.

A sender connector device comprising a 100 plurality of sections 4208 and 4209 serves to connect the senders with any one of a plurality of incoming markers, two of which 4210 and 4211 are shown. These incoming markers are associative through frame connectors 4206 and 4207 respectively with the groups of incoming selector frames 4200 and 4201.

105 A number of final translators 4219 and 4220 are provided. There may be any desired number of these translators, each one pertaining exclusively to a different portion of the subscribers' lines as called lines. Any of the final translators may be associated with the incoming markers.

110 The final translator, 4219 for example, is 115 arranged to make connection with any of the 120

final connector switches of the group 4214 and serves to control any one of these switches to make connection to the called subscriber's line. In a similar manner, the 5 final translator 4220 is associative with the connector switches of a different group, and governs the same to extend connections to other called subscribers' lines.

Referring to Figs. 1 to 40 a more detailed 10 explanation will now be given of the general arrangement of the switches and controlling mechanism. First, with respect to the construction of the line switch, selector switches, the connector switch, and the 15 sender selector, these may be of the same general construction and operation as the switch shown and described in detail in the patent of S. B. Williams No. 1,517,331, issued Dec. 2, 1924, and in the British Patent 20 No. 183,438 to Western Electric Company, Limited, accepted September 6, 1923.

The subscribers' lines appear in the line switches as shown in Fig. 2 of the drawing, there being a plurality of lines assigned to 25 each vertical row. For instance, the lines 100 and 101 appear in the vertical row 201 of the line switch 200. The line 100 is capable of connection with each of a plurality of link circuits, or horizontal links, as 30 they will be called hereinafter. Two of these horizontal links 209 and 210 are shown. The line 101 in the same vertical row has access to the horizontal links 211, 212, etc. of a different horizontal group. In like 35 manner, other lines of the same vertical row have access to other horizontal groups not shown in the drawing. There may be any desired number of vertical rows or groups of lines, one other group 202 being shown. 40 The outgoing trunks, two of which trunks 215 and 216 are illustrated, occupy each a complete vertical row of contacts in the line switch 200 thus intersecting all horizontal links in the switch.

45 The contact controlling bars assigned to the vertical rows illustrated are operated by the respective vertical magnets 205, 206, 207 and 208, while the horizontal operating bars are actuated by the individual magnets 213, 50 214, etc.

The trunks outgoing from the line switches lead to the district selector switches 400 appearing in vertical rows 401, 402, etc. These trunks may be disposed in any convenient manner among the different district 55 selectors of the different groups.

The trunks extending between the line switches and district selectors also appear in the sender selector switch 1200. These 60 trunks appear in the sender selector switch in substantially the same manner as the subscribers' lines appear in the line switches. For instance, the trunk 216, together with trunk 1221 and others, appears in the vertical row 1202. Trunks 1222 and 1223, etc., 65

occupy another vertical row 1201. Trunks 216, 1222, etc., are served by the group of horizontal links 1205 and 1206, while trunks 1221 and 1223, etc. are served by the group of horizontal links 1207 and 1208.

The outgoing circuits from the sender selector switch each lead to separate recording sending mechanisms, and each such circuit occupies a full vertical row of contacts. The circuit 1209, shown in full, occupies the vertical row 1204, and leads to the particular recording sender shown in the drawing. The circuit occupying the vertical row 1203 leads to a different recording sender.

The purpose of the register sender shown in Figs. 14 to 21 inclusive, is to receive and record the designation of desired lines. The receiving portion of the sender shown in Fig. 15 consists of the impulse relays which receive the impulses and in turn operate a series of counting relays 1900 shown in Fig. 19. The first three registers 1901, 1902 and 1903, each comprising a plurality of relays, are for the purpose of recording the three digits which constitute the code designation 90 of the office in which the call is to be completed.

The remaining registers shown in Fig. 21 serve to receive and record the numerical and stations portions of the called line designation.

The relays shown in Fig. 16 are principally for storing class information whereby the sender may properly govern the remaining apparatus in the system to establish the connection involved. This class information is received from the outgoing marker during the time the sender is connected thereto, to be used by the sender after the marker has completed its function, and been disconnected from the sender.

The relay series in Figs. 18 and 20 constitute a switching device by means of which the impulse circuit is associated with the registers and functions as the digits are received over the calling line.

The time measuring device as shown in Fig. 17 commences the counting of time at different points in the functioning of the sender and is arranged to allow a sufficient interval for different duties to be performed by the sender. In case the sender fails to function properly within this interval this time measuring device brings to the attention of a monitoring operator the fact that trouble has been encountered.

Since there are a number of outgoing markers available to all of the district selectors, and since the district selectors are divided into groups, each group having its separate frame connector, it is possible to have two or more outgoing markers functioning simultaneously in the control of the district selector switches, provided the sender connector is so arranged that a plu-

5 rality of markers may be simultaneously connected to respective senders. To this end, the sender connector has a number of separate sections 2200 and 2300. The section 2200 is made up of a plurality of multi-contact relays 2201, 2203, 2204, etc., each such relay being individual to a different one of the recording senders. Furthermore, this section 2200 includes a number of 10 multi-contact relays 2205, 2206, etc., each individual to a different one of the outgoing markers. In a similar fashion a section 2300 of the sender connector is made up of multi-contact relays 2301, 2302, etc., each individual to a separate sender, and relays 2305, 2306, etc., each individual to one of the markers. All of the senders appearing in the section 2200 may be considered as a group of senders, while the 15 senders appearing in the section 2300 comprise a second group of senders. It will be noted that no one sender appears in more than one of these groups, the particular sender illustrated in full in the drawing 20 appearing in the first mentioned group and in the contacts of the multi-contact relay 2201.

25 Each of the outgoing markers has an appearance in each of the different sections 2200 and 2300 of the sender connector. For example, the marker shown in the drawing appears in the contacts of relay 2206 in the section 2300, and also in the corresponding relay 2306 of section 2300. A second marker would similarly appear in the contacts of relays 2205 and 2305 of the respective sections 2200 and 2300. The circuits are arranged to prevent interference so that whenever a marker is connected to a 30 sender through one section of the sender connector, it is rendered non-selectable to any other sender either through the same 35 or through another section.

40 All of the senders appearing in each section of the connector and constituting a group of senders are further divided into a number of subgroups, each subgroup having a different one of the markers as its first choice selection. For illustration, the senders represented by the relays 2201 and 45 2203 constitute a subgroup the senders of which have first choice access to the marker shown in the drawing and represented by the relay 2206. The relay 2204, represents 50 a second subgroup of senders in the section 2200, all of which have first choice access to the marker represented by the relay 2205. In like manner other subgroups may be provided, each to have first choice access 55 to a different marker. The circuits are further arranged in such a way that if a given marker is busy at the time one of its first choice senders is attempting to 60 make connection therewith, such sender may have access to another marker as

second choice, and if such other marker is busy, such sender may have access to a third marker as a third choice, and so on. In short, all of the senders of all subgroups may be associable with any one of the different outgoing markers. The same relation holds in the section 2300 and in other sections of the sender connector. 70

75 As soon as the sender which has received the record from the calling line, has been connected through the sender connector to an idle outgoing marker, the office or code part of the designation is transferred from the registers 1901, 1902 and 1903 through the sender connector to corresponding 80 registers 2500, 2501 and 2502 in the marker.

85 The register 2500 determines the operation of one of a number of multi-contact relays 2701, 2702 and 2703, etc. The register 2501 determines the operation of one or more of the relays 2704, 2705, 2706, 2707. With these relays operated, the register 2502 applies ground potential to one or more of the conductors 2515 which lead through the translator device 2700 and to 90 the distributing frame 2813, causing the operation of one or more of the routing relays 2800.

95 As hereinbefore noted, there are a number of frame connecting devices for connecting the outgoing markers to the district and office frames. There is one of these district frame connectors for each of the different groups of district frames, the purpose being to enable a number of different markers 100 to be simultaneously connected to district switches in the different groups. The district frame connector 2900 is individual to the particular group of district frames, which contains the district switch 400. The connector 2900 consists of a number of multi-contact relays 2906, 2907, etc., each individual to a different one of the outgoing markers. Moreover, it includes a number of 105 multi-contact relays 2908, 2909, etc., each of which is individual to a different district selector in the group. The relay 2906 is seen to be individual to the particular marker shown in the drawing, and relay 2909 is individual to the particular district switch 110 400 shown. Obviously other relays may be provided for additional switches and markers. 115

120 A second one of the district frame connectors 2901 is illustrated diagrammatically in the drawing. It has a plurality of relays each individual to one of the outgoing markers, and also relays each individual to the different selectors of a second group of district frames.

125 Inasmuch as each and every marker has access through each of the district frame connectors to the switches served thereby, it is necessary for a particular marker when taken in use to select the proper one of the 130

frame connectors which reaches the group of district frames to which the calling line has been extended. The manner in which this selection is effected will be taken up in 5 detail hereinafter.

In addition to the district frame connectors, there are provided a number of district trunk connectors, one of which, 2902, is shown partly in detail, and a second of 10 which, 2903, is illustrated diagrammatically. These trunk connectors serve to associate the outgoing markers with the different groups of trunks outgoing from the various district selector switches.

15 For connecting the outgoing markers to the office selector frames in the event of interoffice connections, a plurality of office frame connectors are also employed. One of these, the frame connector 3000 is shown 20 serving to connect any of the outgoing markers to the different office selector switches of a given group. One of the office selector switches 600 of this particular group is shown, while another switch in the same 25 group is represented by the relay 3005 in the frame connector. As in the case of the district frame connectors, other office frame connectors may be provided, each serving to connect the markers to the different office 30 frames of other groups.

Furthermore, office trunk connectors, such as the trunk connector 3001 are provided for connecting the outgoing markers to the different groups of trunks outgoing from the 35 office frames.

Each of the outgoing markers is equipped with a series of testing relays 2400 for testing the horizontal links and the outgoing trunks on any of the district or office 40 switches. Each relay has two windings, one for testing the condition of the corresponding link on any switch frame, and a second winding for testing the trunk having access to such link. There are, therefore, as many 45 testing relays in the series as there are such links and trunks in any vertical row in the switch frames. For convenience in description, it may be assumed that the switch frames have a capacity for 70 horizontal 50 links, and consequently 70 trunks in each vertical row. According to the character of the traffic served, a trunk group may comprise the full 70 trunks in a vertical row of 55 the switch. If small groups are required, a vertical row of contacts may be divided 60 into several groups. For example, a single vertical row may contain one group of 40, a group of 20 and a group of 10 trunks, each of these groups being separate and distinct from the others and going to different 65 destinations. Again a vertical row may be made up of three groups of 20 and a single group of 10 trunks. In other cases it may be desired to employ groups of trunks containing more than 70. In this case it be-

comes necessary to place 70 trunks on a corresponding vertical row of a number of district selectors, and to place the remaining trunks on corresponding rows of other and separate district selectors. For example, if 70 it is necessary to have a group of 140 trunks, 70 of these may be multiplied to half of the district selectors occupying a full corresponding vertical row on each of these, and the other 70 trunks may be similarly multiplied to the other half of the district selectors. In effect, this gives two full groups of trunks going to the same destination. 75

Considering the testing relays again, it 80 will be necessary to divide the entire chain of 70 relays into groups, corresponding to the division of the groups of trunks on the district or office frames. For example, if it be considered that some groups of trunks comprise 20 trunks, the test relays 2400 may 85 be arranged in two groups of 20 and one group of 10, so that only those relays which correspond to the location of a trunk group on the switch frames may be involved in a testing operation. 90

Inasmuch as the present case is devoted 95 more particularly to the establishment of a local connection, the routing of calls through the office selector switches 600 will only be taken up in a general way. It will be noted 100 that the trunks which reach the office selectors appear in the district frame multiples. These trunks occupy the full vertical rows 601, 602, etc., of the office selector 600 being accessible to all horizontal links 605, 606, 105 607 and 608. The trunks occupying the vertical rows 603, 604, etc., comprise groups which extend to distant offices for carrying the interoffice traffic.

For the purpose of local calls, the connections are extended from the district selectors directly to an incoming selector switch 800. It will be assumed that the traffic requires a larger group of trunks between the district and incoming switches than can be 110 accommodated by a single vertical row in the district selectors. Accordingly, it will be assumed in that case that the group of trunks extending from the district frames to the incoming frames comprises 140 trunks 115 made up of two sub-groups of 70 trunks each. Accordingly 70 of these trunks will be multiplied to a portion of the district selector frames, while the remaining 70 will be separately multiplied to another portion 120 of the district selector frames. The manner in which the outgoing marker determines the particular subgroup of 70 involved, will be 125 fully explained in the detailed description to be given hereinafter. One subgroup of 70 trunks may occupy the vertical row of contacts 403 in the district selector 400 and will be multiplied to occupy the corresponding row in a number of other similar district 130 selectors. These trunks, including the trunk

417 extend and appear in the vertical rows of contacts of a number of incoming selector switches, such as the switch 800.

The incoming selector frame is divided 5 into three sections, two of which, 813 and 814 are partially illustrated. Each of these three sections may comprise 23 horizontal link circuits. The incoming trunks appear 10 in the rows 801, 802, etc., each trunk having access to all the horizontal links in only one section. The trunk 417, for instance, appears in the vertical row 802, and is accessible to the links of the section 814.

A number of groups of trunks leading 15 from the incoming switches extend and appear in the vertical rows of the final or connector switches 1000. The connector switches may be arranged in a number of groups, each group of which has access to 20 the corresponding group of called subscribers' lines. In order to reach any desired group of connectors, it is only necessary to select at the incoming switch a group of trunks extending from the incoming switches 25 to the proper group of connectors. These groups of trunks, it will be noted, are multiplied so as to have an appearance in each of the horizontal sections 813, 814, etc., of the incoming switches. In other words, a 30 given group of trunks outgoing from the incoming switches contains 23 trunks, each of which may be reached through a single horizontal link in each of the three sections of the incoming switch. More specifically, 35 the group of trunks 824 appears in the vertical row of contacts 806 of the incoming frame 800 and is also multiplied to appear correspondingly in other incoming frames. The trunks of this group extend and appear 40 in the vertical rows 1001 and 1002 of the connector switch 1000, and are also multiplied to appear correspondingly in the other connector switches of the same connector group.

45 Furthermore, it will be noted that the connector switches are divided into a number of horizontal sections. In this case there are five horizontal sections, each comprises 13 horizontal connecting links and a single 50 horizontal testing link. Two of these sections 1015 and 1016 are illustrated. As in the case of the incoming switches, each of the trunks of a group has a single appearance in each of the five sections of the connector switches.

A second group of 23 trunks 825 extending from the incoming switches may lead to the connector switches of a second connector group. Similarly there are provided as 60 many groups of trunks extending from the incoming switches as there are groups of connector switches in the office.

65 It will be observed that while a group of 23 trunks may be contained in a single vertical row of contacts on the incoming selec-

tors, it is not practical to confine these trunks all on a single vertical row on the final switches. In order to better understand the manner in which these trunks are disposed, reference will be made hereinafter to the diagram of Fig. 43 when an explanation is given of the way in which the trunks are tested by the incoming marker.

70 For the further purpose and description it will be assumed that a group of connectors has access to a group of 1000 called subscribers' lines. Accordingly, for a 10,000 line office there will be 10 of these connector groups, each group may have as many switches as are necessary to serve the full 80 1,000 lines, together with provision for P. B. X. trunks.

75 The called subscribers' lines appear in the connector switches in vertical rows 1101, 1102, etc., each vertical row accommodating 85 five subscribers' lines. The line 1100, for example, appears in the row 1101, and has access to all of the horizontal links in the section 1016. A second line 1110 appears in the same vertical row having access to 90 the horizontal links in the section 1015. A decimal group of ten subscribers' lines therefore, must occupy two vertical rows in the connector switch, five on each row.

95 After the connection has been extended through the district selector switch over a trunk to the incoming selector 800 and the outgoing marker is disconnected from the sender, the sender is immediately connected through the sender connector 3100, to an idle incoming marker. The incoming marker comprises a number of numerical registers, 3400, 3401, 3402, 3403 and 3404 which receive the numerical designation from the sender. Also the marker includes a translator device 100 3600 which is set in accordance with the operation of the numerical registers.

105 The next function to take place is to connect the incoming marker to one of the final translators. Under the present assumption, there being 10 final groups of connector switches and called lines, there should also be 10 final translators, one for each of the different connector groups. For the purpose of connecting the incoming markers to the final translators, there are provided a 110 number of connecting devices as shown in Figs. 38 and 39. One of these connecting devices 3800 serves to connect the markers to the particular final translator illustrated.

115 Another connecting device 3801 shown diagrammatically serves in a similar manner to connect the incoming markers to a second of the final translators. The final translator 4000 is positioned from the numerical registers in the marker, and then cooperates with these registers to select a vertical operating magnet 1106, 1107, 1108 or 1109 on 125 one of the connector switches in the connector group which relates to the vertical 130

row of contacts in which appears the called line on a P. B. X. call number line. The incoming markers are associated with the incoming frames by means of frame connectors 3700 and 3701, each of these being individual to a different group of incoming frames. Moreover, the incoming markers are associated with the trunk group leading from the incoming switch to the final connector group by means of a connecting device 3901. Another of these connecting devices 3903 acts in similar manner to associate the markers with the group of trunks leading to another final connector group. In order to test the horizontal links of any given sections in the connector switches and to operate a desired horizontal magnet, there are provided the connecting devices 3900 and 4001. The device 3900 comprises a number of relays 3904, 3905, each individual to a different incoming marker, and a number of relays 3906, 3907, and 3908, each relating to a different one of the horizontal sections 1015, 1016, etc. The device 4001 comprises a series of relays 4009, 4010, etc., each of which is individual to a different one of the connectors in the group. The schematic 3902 represents another connecting device relating to a second group of connector switches.

The testing of the links in the incoming switches, the trunks leading from the incoming to the selector switches, and the links in the connector switches is all accomplished by a series of testing relays 3300 located in the incoming markers.

Referring to the diagram of Fig. 43 it is assumed that each group of trunks between the incoming and connector switches contains 23 trunks. Since the connector switch is made up of five horizontal groups 4305, 4306, 4307, etc., and each trunk of the group 4308 has an appearance in each section, it follows that only about 13 trunks can be accommodated in a single vertical row on the connector switch, whereas the full group of 23 trunks may be accommodated on a single row in the incoming switch. Consequently, it is necessary to utilize two adjacent rows in the connector switch for each group of trunks. It will be noted that the group of 23 trunks 4308 occupies the full vertical row 4311 in the incoming switch 4300, and extends and occupies the two adjacent vertical rows 4309 and 4310 of the connector switch 4301. The trunk No. 1, for instance, appears in the row 4309 opposite the first horizontal link; the trunk No. 2 appears in the second row 4310 opposite the first horizontal link; the trunk No. 3 appears in the first row opposite the second horizontal link, and the trunk No. 4 in the second row 4310 opposite the second horizontal link. In this manner the trunks are distributed with each odd numbered trunk in the row

4309 and the succeeding even numbered trunk in the row 4310, both appearing opposite the same horizontal link.

Referring now to the testing relays in the marker, it will be seen that these relays must ascertain the condition of the horizontal link in the proper section 4302, 4303 and 4304 of the incoming switch, the condition of the trunks of the desired group extending from the incoming switch, and also the condition of the horizontal links in the section in the connector switch which has access to the called subscriber's line. To this end the testing relay set comprises a number of double wound relays and a number of single wound relays. The first double wound relay serves to test the condition of the first horizontal link in the section 4302 of the incoming switch with one winding and the first outgoing trunk in each group which has access to that horizontal link with the other winding. Similarly, the second double wound relay tests the second horizontal link, and the second trunk in each group. The first single wound relay serves to test the first horizontal single link in the connector switch which is accessible over the first and second trunks of groups coming from the incoming selector switch.

Referring more particularly to the detailed drawings, relay 3301 serves to test the condition of the first horizontal link 815 of the section 813 or the first horizontal link 817 of the section 814, and also to test the condition of the trunk 826 and the corresponding trunk in other groups. The second double wound relay 3302 serves in a similar fashion to test the second horizontal link of any section in the incoming switch and the corresponding trunk of any group outgoing therefrom. The relay 3303 serves to test the condition of the first horizontal link 1005 of the section 1015 and the first horizontal link 1008 of the section 1016, in the final connector switch. It will be noted that the first two trunks in any group outgoing from the incoming selector appear before the first horizontal links 1005, 1008, etc., in the connector switch. For instance, the trunk 826 appears before the horizontal link 1005 in the vertical row 1001 in the section 1015 and also before the link 1008 in the section 1016. The second trunk 827 appears in the second vertical row 1002, and before the corresponding horizontal links in each of the sections.

Relays 3307, 3308 and 3309 comprise the next unit in the series of testing relays and determine the condition of the next two trunks for the second horizontal link in each section of the connector switch.

Inasmuch as a single horizontal link in the connector switch appears before two trunks in any group, if this link is busy at the time a connection is attempted the testing relays

of the marker must render the two corresponding trunks non-selectable whether or not they are busy in fact.

Detailed description of the operation.

5 *Establishment of a local connection.*—Assume that the subscriber of line 100 desires to hold a conversation with the subscriber of line 1100 located in the same office. Consider that the code or office designation of the local office is represented by the abbreviation T. O. K., which in terms of dial impulses is represented by three digits 8, 6, and 5. Assume further that the numerical designation of the line 1100 is 2345.

10 *Operation of the line switch.*—The calling subscriber on removing his receiver from the switchhook, closes an obvious circuit for the line relay 103. Relay 103 closes a circuit for the relay 218, common to all the lines in the vertical row or group 201. This circuit may be traced from the battery through the winding of the vertical group relay 218, left contact of relay 217, outer contact of relay 103 to ground at the left back contact of relay 105. Relay 218 causes the operation of the vertical group control relay 219 by means of a circuit from battery through the left hand winding of relay 219, 15 right front contact of relay 218, back contact of relay 110 to ground at the contacts of the slow operating time measuring relays 111 and 112. Relay 219 closes a holding circuit from battery through its right winding and locking contact, winding of relay 110 to ground. Relay 110 also operates in this circuit and opens the original operating circuit of relay 219.

20 Relay 219 causes the operation of the horizontal group relay 104. The relay 104 is individual to the horizontal group containing the links 209 and 210. Another horizontal group relay 108 is also illustrated. The circuit for relay 104 may be traced from battery through the right winding thereof, right contact of relay 105, inner right contact of relay 103, outer left contact of relay 219, left contact of relay 109, to ground. Relay 104 operates and locks in a circuit from battery through its left hand winding and locking contact, left back contact of relay 108, winding of relay 109 to ground at the contact of the slow operating relays 111 and 112. Relay 109 operates in series with 25 the left winding of relay 104.

30 Relays as 219, also close operating circuits for the vertical magnets of the line switch 200. A circuit for vertical magnet 205 may be traced from battery through the winding of said magnet, middle left contact of relay 219, front contact of relay 110 to ground. Magnet 205 rotates its associated rod and prepares the contacts in the vertical row 201. Another circuit is closed for operating the 35 vertical magnet associated with the first idle

outgoing trunk, and may be traced from ground through the front contact of relay 110, inner left contact of relay 219, lower front contact of relay 220 (assuming the first trunk 215 to be busy) lower back contact of relay 221, through the winding of magnet 208 to battery. Magnet 208 prepares the contacts in the vertical row in which the idle outgoing trunk 216 appears.

40 With both vertical magnets 205 and 208 energized a circuit is closed for operating the timing relay 111. This circuit may be traced from ground, through the lowermost contact of magnet 208, lowermost contact of magnet 205, winding of relay 111 to battery. Relay 111 commences to energize and after an interval attracts its armature and closes a circuit for relay 112. Relay 112 likewise requires an interval in which to attract its armature. With both relays 111 and 112 operated, ground potential is removed from the holding conductors to permit the release of the control relays. During the intervals required for the operation of these time measuring relays, however, a circuit is closed for operating the horizontal magnet of the first idle link having access to the calling subscriber's line and to the outgoing trunk. This circuit may be traced from ground through the lower contact of magnet 208, middle contact of magnet 205, right contact of relay 109 which is energized in series with relay 104, right contact of relay 104, right front contact of relay 106 (assuming the first link 210 and its operating magnet 213 to be in use) right back contact of relay 107 (assuming the second link 209 to be idle) right winding of magnet 214 to battery. The magnet 214

45 rotates the associated rod and effects connection between the calling line 100 and the outgoing trunk 216. Immediately that the connection is established a circuit is closed from battery through the two windings of magnet 214, winding of relay 107, contacts of the switch 200, conductor 222, contact of magnet 208 to ground. Relay 107, however, does not operate at this time, since its winding is shunted by the circuit previously traced for magnet 214.

50 The application of ground potential to the conductor 222 causes the operation of relay 221, which identifies the trunk 216 as busy and extends the start wire 223 on to the next trunk. The application of ground to the conductor 222 also causes the operation of the cut-off relay 102. The circuit leading through the contacts of the relay 102 now being opened the line relay 103 releases.

55 From the time the vertical magnet 208 operates and applies ground potential to the sleeve conductor 222 until the slow relay 112 operates a sufficient interval elapses to permit the operation of the sender selector

switch 1200 and the association of an idle sender with the calling line. When this sender is associated it extends a holding ground back to the line switch 200 to hold 5 the same operated following the operation of relay 112 in the manner to be explained hereinafter.

The operation of the sender selector switch and attachment of an idle sender.—

- 10 When magnet 208 first operates, it causes the operation of relay 1300 in a circuit from grounded conductor 222 inner upper back contact of relay 301, inner lower contact of said relay, innermost lower back contact of 15 relay 305, conductor 307, winding of relay 1300 to battery. Relay 1300 operates and locks in a circuit from battery through its winding and locking contact, conductor 308 to ground at the back contact of slow release relay 306. Relay 1300 operates the relay 305 in a circuit from ground through the outer left contact of relay 1300, conductor 309, winding of relay 305 to battery.

20 Relay 305 locks in a circuit from battery through its winding and locking contact, inner lower contact of relay 301, conductor 311, through the inner upper contact of relay 305 to ground.

25 Relay 305 prepares a circuit for the left hand winding of relay 312, which is closed at another point by the interrupter 313, making at its lower contact. Relay 312 however, has its circuit open at this time at the contact of relay 304 which it will be 30 noted is energized in series with the calling subscribers' lines and the left hand windings of the repeating coil 302.

35 The relay 1300 initiates the operation of the control relays of the sender selector 1200 40 to cause the actuation of said switch in substantially the same manner as already described in connection with the line switch 200. Relay 1300 completes a circuit for the operation of relay 1215 which leads through 45 outer right contact of relay 1300 to ground at the contact of relay 1302. Relay 1215 causes the operation of relay 1216, which in turn locks in series with the relay 1307. Relay 1216 also closes a circuit for the horizontal group relay 1301 which locks in series 50 with relay 1306. Relay 1216 furthermore closes an operating circuit for the vertical magnet 1211 which prepares the contacts in the vertical row 1202.

55 The relay 1216 also closes a circuit for operating the first vertical magnet 1212, 1213, etc., representing an idle register sender. This circuit may be traced from ground through the inner left contact of 60 relay 1216, outer right front contact of relay 1217 (assuming the first register sender indicated is busy) outer right back contact of relay 1218, conductor 1224, winding of the vertical magnet 1213 to battery. With magnets 1211 and 1213 operated, a circuit is

closed in the manner above explained for operating one of the horizontal magnets to extend the trunk through the switch 1200 to the idle register sender. This circuit may be traced from ground through the 70 lowermost contact of magnet 1213, lower middle contact of magnet 1211, conductor 1310, contact of relay 1303 (this latter relay having operated when relay 1301 attracted its armatures), right back contact of relay 1304, winding of the horizontal magnet 1220 to battery. Another circuit is closed as above explained for operating the time measuring relays 1309 and 1308.

When relay 1216 operated and applied 80 ground potential to conductors 1224 and 1511, a circuit was also closed for relay 1505 in the sender. Relay 1505 applies holding ground potential to the conductor 1511, holding the magnet 1213 operated through a 85 contact of relay 1219. Furthermore, the application of this ground potential to conductor 1511 results in a holding circuit for the horizontal magnet 1220 traceable from battery through both windings of said magnet, winding of relay 1304, through contacts of switch 1200 to grounded conductor 1511. Relays 300 and 306 now operate. The circuit for these relays may be traced from 90 battery through their windings in parallel, conductor 314, through contacts of the switch 1200 to the grounded conductor 1511. Relay 306 at its right front contact applies ground to conductor 311 whereby the horizontal magnet 214 of the line switch is held 95 energized. When relay 112 subsequently operates, relay 306 by removing ground from conductor 308 also causes the release of relay 1300.

100 The relay 300, in operating, opens the circuit of relay 304 and extends the calling line through to the impulse relay 1500. The impulse circuit may be traced from battery through the right winding of relay 1500, outer right contact of relay 1510, conductor 1512, through the switch 1200, conductor 1225, inner lower contact of relay 300, contacts of switch 200, ring side of the calling line, through the subscriber's station apparatus, back over the tip side of the line, contacts of switch 200, upper inner contact of relay 300, conductor 1226, through the switch 1200, conductor 1513, inner right contact of relay 1510, right hand winding of the balancing coil 1501 to ground.

110 When the slow relays 111 and 112 finally operate, they cause the release of relays 219, 109, 110 and 104, and also the release of the vertical magnets 205 and 208. Relay 107 now operates in series with the magnet 214, and both are held by the sender as explained before.

115 When relay 1308 operates, it causes the operation of trunk relay 1219 in a circuit from battery through the winding of relay 1200

1219, contact of magnet 1213, contact of relay 1308 to ground. Relay 1219 locks to the grounded conductor 1511 and opens the holding circuit of magnet 1213 which extended temporarily to the grounded conductor 1511. Before relay 1219 operates, as explained, and while relay 1505 in the sender is energized, the relay 1503 becomes operated in a circuit from battery through the 10 left back contact of relay 1219, right back contact of relay 1514, outer right contact of relay 1505, winding of relay 1503 to ground. Relay 1503 closes a circuit for slow release relay 1502, in order that the same 15 may be prepared when the impulse circuit is completed.

When the slow release relays 1309 and 1308 finally operate they cause the release of the control relays associated with the 20 sender selector 1200 and also the release of the vertical magnets 1211 and 1213. Relay 1304 operates in series with the horizontal magnet 1220, and both are held by ground potential on conductor 1511 supplied by the 25 sender. The subscriber's line is thus extended to the register sender.

Recording the called number on the sender.—When the impulse relay 1500 operates it closes a circuit for relay 1502 as follows: Battery through the winding of relay 1502, outer left back contact of relay 1503 (which released when trunk relay 1219 operated), front contact of relay 1500 to ground.

35 Relay 1502 operates the relay 1400 in a circuit from battery, through the winding of relay 1400 to ground at the left front contact of relay 1502. Relay 1400 operates the relay 1504 in a circuit from battery through the left winding of relay 1504, left front contact of relay 1400 to ground at the outer left contact of relay 1505. Relay 1504 locks through its right winding and locking contact to the inner left hand contact of relay 1505. Relay 1500 on first energizing also operates the counting relay 1913 in a circuit from ground through the front contact of relay 1500, conductor 1515, outer left contact of relay 1800, conductor 40 1811, right back contact of counting relay 1906, inner right back contacts of relay 1908, 1910 and 1912, winding of relay 1913 to battery. Relay 1913 operates and prepares a holding circuit for itself and relay 1912 to 45 battery. Relay 1913 operates and prepares a holding circuit for itself and relay 1912 as follows: Battery through the windings of said relays in series, right contact of relay 1913, left back contact of relay 1910, conductor 1930, left normal contact of relay 1800, conductor 1812, contact of holding relay 1504 to ground. Relay 1912, however, is shunted at this time, and does not operate.

When relay 1400 operated it closed a circuit for the application of dialing tone current. This circuit may be traced from

5 ground at the tone current source 1804, inner right contact of relay 1802, left hand winding of the balancing coil 1501, left front contact of relay 1400 to ground at the outer left contact of relay 1505. Current is induced in the right hand winding of 70 the coil 1501, which produces a characteristic sound in the subscriber's receiver notifying him that the apparatus is ready for the transmission of impulses.

The calling subscriber manipulates his 75 dial to transmit a series of eight impulses representing the first letter "T" of the office designation. On the first interruption of the line circuit, relay 1500 releases and operates the slow to release relay 1803. The circuit for this purpose leads from ground through the back contact of relay 1500, right contact of relay 1502, inner left contact of relay 1503, conductor 1516, winding of relay 1803 to battery. Relay 1803 operates the relay 1801 by means of a circuit from battery through the winding of relay 1801, right normal contact of relay 1800, front contact of relay 1803 to the grounded conductor 1812. Relay 1801 locks through its left 80 front contact independently of relay 1803.

Also on the first interruption, relay 1500 removes the shunt from around the winding of relay 1912 which operates in series with relay 1913. At the end of the first interruption, relay 1500 operates, recloses the circuit of relay 1502 and also applies ground to conductor 1515, which is now extended over conductor 1811, right back contact of relay 1906, inner right back contact of relays 1908 and 1910, inner right front contact of relay 1912, winding of relay 1911 to battery. Relay 1911 operates and prepares a circuit for itself in series with relay 1910 in the manner above described.

100 Relay 1500 in operating at the end of the first interruption opens the circuit of relay 1803. The relays 1803 and 1502, however, being slow to release maintain their armature attracted during the repeated interruptions of their circuits as the impulses are being transmitted. Upon the next interruption of the line, relay 1910 operates in series with relay 1911 and opens the holding circuit of relays 1915 and 1912, permitting 105 these latter relays to release.

110 At the end of the second interruption of the line, relay 1909 operates and prepares a circuit for itself in series with relay 1908.

115 On the beginning of the third interruption of the line, relay 1908 operates and releases the counting relays 1911 and 1910. At the end of the third interruption, counting relay 1907 is operated and prepares a circuit for relay 1906.

120 At the beginning of the fourth line interruption, counting relay 1906 operates and opens the holding circuit of relays 1909 and

1908. At the end of this interruption relay 1905 operates, and prepares a holding circuit for itself and relay 1904, traceable as follows: Battery through the windings of relays 1905 and 1904, right contact of relay 1905, left back contact of relay 1912 to the grounded conductor 1930.

On the beginning of the fifth line interruption, relay 1904 operates and releases 19 relays 1907 and 1906. At the end of the fifth line interruption, the impulse circuit is extended by way of conductor 1811 through the right front contact of relay 1904, inner right back contact of relays 1908, 1910 and 1912, winding of relay 1913 to battery. Relay 1913 operates. Another circuit is completed at this time for operating the counting relay 1931, traceable from battery through the winding of said relay, 20 outer right contact of relay 1800, left back contact of relay 1932, outermost right contact of relay 1904, right normal contact of relay 1800, left front contact of relay 1801, to the grounded conductor 1812. Relay 1931 25 operates and prepares a circuit for itself and relay 1932 to the grounded conductor 1930, relay 1932 being shunted, however, does not operate at this time.

At the beginning of the sixth line interruption, the shunt is removed and relay 1912 operates, relay 1912 releases relays 1904 and 1905, and relay 1904 in turn removes the shunt to permit relay 1932 to operate. At the end of the sixth interruption counting 30 relay 1911 is again operated as above described.

At the beginning of the seventh line interruption, relay 1910 operates and opens the circuit of relays 1913 and 1914. At the 40 end of the seventh interruption, relay 1909 operates and prepares a circuit for relay 1908.

At the end of the next and last interruption relays 1911 and 1910 have been released 45 and relays 1909, 1908, 1907, 1931 and 1932 are in their operated condition.

At the time relay 1803 first operates, it 50 operates relay 1806 in a circuit from battery, through the winding of the latter relay, inner left back contact of relay 1805, front contact of relay 1803, to the grounded conductor 1812. Relay 1806 closes a holding circuit for itself from battery through its winding, winding of relay 1805, inner contact of relay 1806, outer right front contact of relay 1802, to the grounded conductor 1812. Relay 1805, however, is shunted and does not operate. Relay 1806 operates the cut-in relay 1914 in a circuit from ground through 55 the outer contact of relay 1806, outer right contact of relay 1805, winding of relay 1914, to battery. Relay 1914 associates the counting relay set 1900 with the first register 1901.

60 65 After an interval, the slow relay 1803 re-

leases, and circuits are closed for operating the register relays 1915, 1916 and 1918. These circuits may be traced from the grounded conductor 1812, back contact of relay 1803, right contact of relay 1801, thence through the outer right contacts of relays 1912 and 1908 in parallel and also in parallel through the middle right contact of relay 1904, right front contact of relay 1932, left contact of relay 1931, and thence 70 through the contacts of relay 1914 and the windings of relays 1915, 1916 and 1918 to battery. With the register relays energized, the relay 1800 is operated in a circuit from battery through the winding of said relay, outer left contact of relay 1805, thence through contacts of the operated register relays, conductor 1933, right contact of relay 1801, back contact of relay 1803, to ground. Relay 1800 opens the holding circuit of relay 1801. When relay 1801 is released, the shunt is removed from relay 1805, and this relay operates in the following circuit: Battery through the windings of relays 1806 and 1805, inner left contact of relay 1806, outer right front contact of relay 1802 to grounded conductor 1812. It will be noted that relay 1802 always 80 operates an any digit greater than one in an obvious circuit closed at the contact of counting relay 1809. Relay 1802 in operating, locks through its own contact to conductor 1812.

Relay 1801 upon releasing opens the circuit of relay 1800 which in turn releases. During the time relay 1800 is energized, the holding circuits of the counting relay are opened and these relays restored to normal.

Relay 1805 in operating opens the circuit of relay 1914, which releases and disconnects the counting relays from the register 1901. The operated register relays 1915, 1916 and 1918 remain energized in locking circuits through their windings in parallel, and thence through their inner left contacts, conductor 1934, through the right outer front contact of relay 1802 to the grounded conductor 1812.

The subscriber next transmits a series of 115 six impulses representing the letter "O" in the manner fully described hereinbefore. The six interruptions of the line result in relays 1913, 1912, 1911, 1931 and 1932 of the counting relay set 1900 being energized.

When relay 1803 operates during the second series of impulses it energizes relay 1808 in a circuit from battery through the winding of the latter relay, inner left back contact of relay 1807, inner left front contact of relay 1805, front contact of relay 1803 to the grounded conductor 1812. Relay 1808 prepares a circuit for relay 1807, which however does not operate at this time. Relay 1808 operates the cut-in relay 1919 120 in an obvious circuit.

After an interval has expired the slow relay 1803 releases and causes the operation of register relays 1920 and 1923 of the second register 1902. The circuit for operating these relays leads from ground through the outer contact of relay 1803, right contact of relay 1801, thence through the outer right contact of relay 1912 and in parallel through the middle right contact of relay 1904, right front contact of relay 1932, left contact of relay 1931, thence through contacts of relay 1919, windings of relays 1920 and 1923 to battery. Relays 1920 and 1923 lock through their inner left contacts to ground at the outer contact of relay 1806. In the manner above explained the register releases, causing the operation of relay 1800, which in turn causes the release of relay 1800. When relay 1801 releases, it opens the shunt around relay 1807 which operates in the following circuit: Battery through the windings of relay 1808 and 1807, inner contact of relay 1808 to ground at the outer contact of relay 1806.

25 For the next arbitrary letter "K" of the office designation the subscriber transmits a series of five impulses at the end of which counting relays 1913, 1905, 1904 and 1931 are operated.

30 When relay 1803 reoperates at the beginning of the third series of impulses, it operates the relay 1810 over a circuit leading through the front contacts of relays 1807 and 1805. Relay 1810 prepares a circuit for relay 1809 which being shunted, does not operate at this time.

After an interval following the third series of impulses, relay 1803 releases and ground is extended through the right back contact of relay 1932, left contact of relay 1931, contact of relay 1924, winding of register relay 1928 to battery. Relay 1924 has already been operated from the front contact of relay 1810 as above explained. Relay 1928 locks through its own contact to ground at the outer contact of relay 1808. Relay 1928 causes the operation of relay 1800, which releases relay 1801, which in turn releases relay 1800. Relay 1801 removes the shunt from relay 1809 which now operates in series with relay 1810. The operation of relay 1800 releases the counting relays as explained, and the operation of relay 1809 releases relay 1924.

55 Next the subscriber transmits a series of two impulses, causing the operation of counting relays 1911, 1910 and 1909. Relay 1803, which operates on the first line interruption, operates the relay 2001, which prepares a circuit for the operation of relay 2000. Relay 2001 operates the cut-in relay 2105.

After an interval, relay 1803 releases, and extends ground through the contact of re-

lay 1910, thence through the contact of relay 2105, thence in parallel through the windings of relays 2107 and 2124 to battery. Relay 2107 locks through its own contact to ground at the contact of relay 1810. Relay 2107 also causes the operation of relays 1800 and 1801 in the manner explained whereby the counting relays are released and relay 2000 operates in series with relay 2001 to ground at the contact of relay 1810. Relay 2000 in operating releases relay 2105.

Next the calling subscriber sends a series of three impulses, resulting in the operation of counting relays 1909, 1908, and 1907. When relay 1803 operates, it causes the operation of relay 2003 in a circuit leading through front contacts of relays 2000, 1809, 1807 and 1805. Relay 2003 prepares for the operation of relay 2002, and also operates the relay 2110.

After an interval, relay 1803 releases, and circuits are completed through the outer right contact of relay 1908 and thence in parallel, one branch leading through the outer right contact of relay 1907 and both branches extending through contacts of relay 2110, windings of relays 2111 and 2112 to battery. Register relays 2111 and 2112 lock through their contacts to ground at the contact of relay 2001. The register relays also cause the operation of relays 1800 and 1801 to release the counting relays and to remove the shunt from relay 2002. Relay 2002 in operating releases relay 2110.

For the next digit the subscriber transmits four impulses resulting in the operation of counting relays 1907, 1906 and 1905. At the time relay 1803 operates on the first interruption of the line, relay 2005 is energized in a circuit leading through the contacts of relays 2002, 2000, etc. Relay 2005 prepares for the operation of relay 2004, and also causes the operation of relay 2115.

After an interval slow relay 1803 deenergizes, and a circuit is closed through the contact of relay 1906, thence through a contact of relay 2115, winding of register relay 2117 to battery. Relay 2117 locks through its own contacts and causes the operation of relays 1800 and 1801 to release the counting relay 1906 and to effect the removal of the shunt from the relay 2004. Relay 2004 causes the release of relay 2115.

Finally the calling subscriber transmits a series of five impulses, causing the operation of relays 1913, 1905, 1904 and 1931 as above explained. When relay 1803 operates, it causes the operation of relay 2007, which prepares for the operation of relay 2006. After an interval expires following the last impulse, relay 1803 releases and a circuit is completed through contacts of relays 1932

and 1931 for the operation of register relay 2123, the cut-in relay 2119 having operated through a front contact of relay 2007. Relay 2123 locks through its own contact, and 5 causes the operation and release of relays 1800 and 1801, in turn releasing the counting relays and permitting the operation of relay 2006. In a manner similar to that hereinbefore described, relay 2006 releases 10 the relay 2119.

The complete office and numerical designation has thus been transmitted and recorded on the register sender in the office. In the present case, the called line was assumed to 15 be a trunk line. Where party lines are concerned, an extra digit will be sent corresponding to the party letter which is recorded on the stations' register 2104. The next step in the sequence of operation is 20 the connection of the sender to an outgoing marker. Before proceeding with a description of this, an explanation will be given of the manner in which a record is established in the sender for the purpose of later 25 identifying to the marker the particular group of district frames to which a calling line has been extended whereby the marker may make connection through the proper frame connector to this group of district 30 switches.

Inasmuch as the district switches are divided into groups the trunks leading to these switches may be correspondingly grouped by giving the trunks of the different groups a systematic location in the 35 sender selector switches 1200. A discriminating indication may be conveyed to any sender, enabling it to record that the calling line has been extended over a particular 40 group of trunks to the corresponding group of district switches. To illustrate more specifically one manner in which this location of trunks can be assembled is to segregate all of the trunks leading to a given 45 group of district frames on one or more of the vertical rows of contacts in the sender selector switches, that is to say, the trunks of a given group may occupy one or more of the vertical rows 1201 and 1202, etc., on 50 the sender selector exclusively. In the present case it may be assumed that the trunks 216 and 1221 and other trunks which appear in the vertical row 1202 all represent 55 the same group and lead to the same group of district selector switches. Also the trunks appearing in the vertical row 1201 may extend to a second group of district selectors. Each of the vertical magnets 1211, 1210, etc., therefore represents a particular 60 group of district frames and by connecting the front contacts of these switch magnets to the distributing frame 1227, and by properly wiring the frame the proper group of district switches may be associated. A

ground potential may be applied to either 65 conductor 1228 or 1229 leading to the sender whenever one of the vertical magnets of the sender selector is operated.

The conductors 1228 and 1229 extend to the recording relays 1506 and 1507. One 70 of these relays represents one group of district switches, while the other relay represents a different group of district switches. Obviously other relays may be provided for other groups of switches. In the present 75 case, it is assumed that the district selector switch 400 shown, to which the calling line has been extended, is in the group represented by the vertical magnet 1211 of the sender selector, and by the recording relay 80 1507 in the sender. Accordingly, at the time relay 1503 operates as explained, and while the magnet 1211 is still energized a circuit is completed from ground through the inner contact of relay 211, through the 85 distributing frame 1227, conductor 1229, middle right contact of relay 1503, winding of relay 1507 to battery. Relay 1507 operates and locks to ground at the contact of relay 1505. The function of the relay 1507 90 will be explained later on, after the sender has been attached to the marker.

Connection of the recording sender to an idle outgoing marker.—At the time the third series of impulses representing the 95 last code letter of the office designation is received and recorded on the register 1903, the operation of the sender connector shown in Figs. 22 and 23 is initiated for the purpose of connecting the sender to an idle 100 outgoing marker. For this purpose relay 1509 is operated in a circuit from battery through its winding, left back contact of relay 1508, outer left contact of relay 1517, conductor 1518, right contact of relay 1810, 105 left back contact of relay 1801 to the grounded conductor 1812. Relay 1509 locks through its right contact, normal contact of relay 1508, normal contact of relay 1507, conductor 1519, to ground at the outer right 110 contact of relay 1504. Relay 1509 operates relay 2207 of the sender connector, which latter relay is individual to the sender shown. The circuit for operating this relay may be traced from battery through the left contact of relay 1509, conductor 1520, conductor 1935, upper winding of relay 2207, right contact of relay 2209, lower back contact of relay 2208 to ground. Relay 2207 operates, and locks through its lower 115 winding and contact and the winding of relay 2208 to ground. Relay 2208 operates and prevents any other sender in the same group having access to the markers through the section 2200 since the operating circuit 120 for relays corresponding to the relay 2207 is opened.

Relay 2207 operates the multi-contact re-

lay 2201 individual to the sender shown, in a circuit from battery through the winding of said latter relay, upper contact of relay 2207 to ground at the lower front contact of relay 2208. The marker shown in the drawing is the preferred marker for the sender which appears in the contacts of relay 2201 in the section 2200 of the sender connector. If this marker is idle the make-busy relay 2214 is deenergized and relay 2207 in operating operates the relay 2215. The circuit for this purpose may be traced from battery through the inner upper contact of relay 2207 contact of relay 2213, contact of relay 2214, front contact of the multi-contact relay 2201, thence through the lower back contact of relay 2214, lower winding of relay 2215 to ground at the contact of the common relay 2216. Relay 2215 locks a circuit from ground through the winding of relay 2216, upper front contact and upper winding of relay 2215 and thence to battery through the contact of relay 2207. Relay 2216 operates in this circuit and causes the operation of the multi-contact relay 2206 which represents the marker illustrated in the drawing. The circuit for relay 2206 leads from battery through the winding of said relay, inner lower contact of relay 2215 to ground at the outer front contact of relay 2216. Relay 2216 also closes an obvious circuit for the make-busy relay 2214 to render the marker non-selectable by other senders. Moreover, relay 2216 operates the relay 2213 in a circuit from battery through the winding of relay 2213, lowermost contact of relay 2215 to ground at the inner contact of relay 2216. When relay 2206 operates it closes a circuit for the relay 2209 traceable from battery through the right winding of said latter relay, contact of relay 2206, thence to ground at the lower front contact of relay 2208; relay 2209 at its right contact removes ground potential from the winding of relay 2207 and all other corresponding relays to prevent the operation of any one of these by another calling sender, even though the relay 2208 may be released. With the multi-contact relays 2201, and 2206 operated as explained, the conductors from the register sender are extended through the sender connector to the selected outgoing marker.

Since the marker illustrated also appears in the section 2300 of the sender connector, it is necessary to render this marker non-selectable to senders of the group which appear in the section 2300. Consequently, the make-busy relay 2310, individual to the marker thus taken, is energized in a circuit from battery through its upper winding, conductor 2311 to the ground at the inner contact of relay 2216. With the relay 2310 operated, it will be impossible to operate the relay 2312, and therefore impossible to oper-

ate the multi-contact relay 2306 to make a double connection to the same marker.

Assuming that the outgoing marker shown is busy at the time the sender desires to obtain connection therewith, then relay 2214 will be operated at the time relay 2207 is energized. It may also be assumed that the marker represented by the multi-contact relay 2205 is the second choice marker for the subgroup of senders containing the sender shown in full in the drawing, and is idle at this time. Consequently, relay 2210 will be deenergized at the time relay 2207 is operated. Under these conditions, a circuit is established from battery through the inner upper contact of relay 2207, contact of relay 2213, upper contact of relay 2210, front contact of relay 2201, lower front contact of relay 2214, upper back contact of relay 2215, thence through the back contact of relay 2204, and through the back contacts of all other similar relays in the same subgroup, lower back contact of relay 2210, lower winding of relay 2211 to ground at the back contact of relay 2212. The purpose of extending the operating circuit of relay 2210 through the back contacts of relay 2204 and the other relays in the same subgroup is to ascertain whether or not one of these senders is seeking connection to its preferred marker, which is represented by the relay 2205. It will be noted that the lower winding of relay 2214 is included in parallel with relay 2211 but the latter relay could not operate in series with relay 2214 due to the resistance of the said relay 2214. If none of the senders of the latter group is attempting connection to its preferred marker, then it is proper for the sender shown in the drawing to choose this marker as its second choice. Consequently, relay 2211 is operated, and in the manner herein-after explained brings about the extension of the sender through the section 2200 to the corresponding marker.

By providing a plurality of sections 2200 and 2300 with the non-interfering circuits described, it is possible for senders in different groups to be connected to idle markers simultaneously.

In case connections are being extended through each of the sections 2200 and 2300 simultaneously, a second connection cannot be extended through either section until the simultaneous connection in the other section has been completed. This end is attained by means of the relays 2209 and 2313. When the relay 2209 operates as explained, it locks in a circuit through its left winding and contact, left back contact of relay 2313, to ground at the upper front contact of relay 2314. Relay 2209, therefore, cannot release to permit the extension of another connection through section 2200 until relay

2314 has become deenergized or until relay 2313 has energized.

Immediately that the sender is connected to the marker relay 2708 is operated in a circuit traceable from ground through the winding of said relay, conductor 2713, contacts of the connector 2200, conductor 1520, to battery through the left front contact of relay 1509. Relay 2708 initiates the transfer of the record from the registers 1901, 1902 and 1903 of the sender to the corresponding registers 2500, 2501, 2502 of the marker.

Transfer of office record from sender to the outgoing marker.—Relay 2708 completes a circuit from ground through its outer right contact, left back contact of relay 2709, back contact of relay 2711, conductor 2714, contacts of connector 2200, conductor 1936, right back contact of relay 1521, conductor 1522, thence through the inner right back contacts of all the unoperative relays of registers 1901, 1902 and 1903 in parallel over conductors 1937, 1938 and 1939, through the connector 2200, and thence through the windings of all the relays of registers 2500, 2501 and 2502 to battery. These latter relays all operate and close a series circuit for operating relay 2710. This circuit may be traced from battery through the winding of the latter relay, and thence through contacts of all the marker register relays in series to ground at the left contact of relay 2511. Relay 2710 locks to the grounded conductor 2715, and operates the relay 2711. Relay 2711 in turn operates the relay 2712. Relay 2711 at its back contact opens the circuit above traced for operating all of the register relays in the marker. These relays thereupon release, with the exception of those relays which correspond to the operated relays in the registers of the sender.

For example, the relay 2503 which corresponds to relay 1915 remains operated in a circuit from battery through the winding of relay 2503, conductor 2516, through the sender connector and thence through the inner right front contact of relay 1915 to ground. In a similar manner circuits may be traced for holding energized the relays 2504, 2506, 2507, 2510 and 2514, which correspond respectively to relays 1916, 1918, 1920, 1923 and 1928.

The next step is to operate the translator 2700 from the register relays in the marker to select one or more of the routing relays shown in Fig. 28. These routing relays each relate to a different one of the groups outgoing from the district and office selector switches. In the present case, which involves a local call, it is necessary to select a group of 70 trunks extending from the district selectors to the incoming selector switches. As hereinbefore mentioned, 70 of

these trunks appear in the vertical row 403 of the district 400 and also a number of other district switches. The other subgroups of 70 are similarly modified to appear in a number of other district selectors. Inasmuch as a total group is divided in two subgroups, there are provided 2 routing relays relating to the total group, each individual to a separate subgroup. It may be assumed that the routing relays 2804 and 2805 are assigned to the group of 70 trunks 75 to be employed for this connection. Accordingly, both of these relays will be prepared for operation, but as will be seen later, only the particular one, which is individual to the subgroup of trunks appearing in the district selector 400 will be operated, inasmuch as the other subgroup of 70 trunks will not be concerned for this particular connection.

The register 2500 with the setting given causes the operation of the multi-contact relay 2703 in a circuit from battery to the winding of said relay, thence through the inner right front contact of relay 2504, outermost right contact of relay 2506, inner right front contact of relay 2503, conductor 2517, contact of relay 2712 to the grounded conductor 2445. The register 2501, with the setting given, causes the operation of relay 2706 in a circuit traceable from battery through the winding of said relay, thence through the inner right back contact of relay 2508, outermost right contact of relay 2510 inner left front contact of relay 2507 to the grounded conductor 2517. With the translator 2700 set, a circuit is completed from the grounded conductor 2517, through the inner right back contact of relay 2511, middle right contact of relay 2514, inner right back contact of relay 2513, outer right back contact of relay 2512, conductor 2716, contact of relay 2706, contact of relay 2703, conductor 2717, through the distributing frame 2813, and thence to one terminal of each of the windings of relays 2804 and 2805. As will be seen hereinafter, the other terminal of one of these windings will have battery connected thereto at the proper time.

Operation of district frame connector and connection of the outgoing marker to the district selector.—While the foregoing operations have been taking place, the outgoing marker has also been in the act of associating itself with the proper group of district selector frames by means of a corresponding one of the frame connectors 2900 and 2901. The instant the sender is connected to the outgoing marker, the district frame connector relay 2409 is operated. This relay relates to the frame connector 2900, and when operated instructs the marker that it must use that particular frame connector for reaching the proper group of district selec-

tors. The other frame connector relay 2410 similarly relates to the frame connector 2901. The circuit for relay 2409 may be traced from ground through the right contact of relay 1507, conductor 1814, through the sender connector 2200, conductor 2518, winding of relay 2409 to battery. Relay 2409 operates the relay 2904, which is individual to the marker shown. The circuit for this purpose may be traced from battery through the inner left contact of relay 2708, conductor 2718, right contact of relay 2402, contact of relay 2409, right winding of relay 2904 to ground at the contact of relay 2905. Relay 2904 operates and locks in a circuit through its left winding and locking contact, left back contact of relay 2920, winding of relay 2905 to ground. Relay 2905 also operates and prevents any other marker from appropriating the frame connector 2900. Relay 2905 closes an obvious circuit for the multi-contact relay 2906 which extends the various leads from the marker through to the grid wires of the connector 2900.

At this time, the vertical operating magnet 410, individual to the row of contacts 401 in the selector 400 in which appears the trunk 216, is operated. The circuit for this purpose may be traced from battery through the winding of said magnet, conductor 418, right outer contact of relay 315, upper front contact of relay 300, thence over conductor 316, through the sender selector switch 1200, conductor 1230, thence over conductor 1523, through the sender connector 2200, conductor 2519, inner left back contact of relay 2406, conductor 2432, inner right contact of relay 2904 to ground at the front contact of relay 2905. It will be noted that the relay 2411 also operates in parallel with the vertical magnet 410. Magnet 410 prepares the contacts in the vertical row 401. Magnet 410 also operates the multi-contact relay 2909, individual to the switch 400, in a circuit from battery through the winding of said relay, inner front contact of magnet 410, and thence over conductor 418 to ground as above traced. Relay 2909 connects the grid wires of the frame connector 2900 to the conductors leading to the switch 400. With the frame connector 2900 operated, the vertical magnet 410 and relay 2909 are locked in parallel circuits, extending through the frame connector, thence over the conductor 2921, conductor 2433, left contact of relay 2403, conductor 2520, to ground at the contact of relay 2708.

Relay 315 is also operated at this time in a circuit from battery through its left winding, conductor 317, lowermost contact of magnet 410, contacts of frame connector 2900 to ground. Relay 315 locks through the left front contact of relay 306 to grounded conductor 314.

Since the multi-contact relays 2908, 2909,

etc., are each individual to a district selector switch 400, the identity of these switches may be established in the frame connector 2900, for the purpose of determining which one of the routing relays shown in Fig. 28 ⁷⁰ should be operated. It will be recalled that in the present case, both relays 2804 and 2805 were prepared for operation, only one of these however, is needed, which is the one that is individual to the group of 70 trunks ⁷⁵ appearing in the district selector frame 400. Accordingly the relay 2909 has certain of its contacts arbitrarily wired to ground, one of which identifies the district selector frame 400. Accordingly, relay 2811 is operated in ⁸⁰ a circuit traceable from battery through the winding of said relay conductor 3012, through contacts of the frame connector 2900 to ground. Relay 2811 completes a circuit for operating the routing relay 2805 to the ⁸⁵ exclusion of relay 2804. This circuit may be traced from battery through the middle contact of relay 2811, thence through the winding of relay 2805, and over the circuit previously traced to ground. ⁹⁰

Operation of the district trunk connector to connect the outgoing marker to the group of trunks.—Now that the routing relay 2805 has been selected and operated, the necessary information is available for telling the ⁹⁵ marker to which group of trunks leading from the district frames it should make connection. As will be seen presently, the trunk connector 2902 is the one employed for connecting the marker to this trunk group. ¹⁰⁰ First, the relay 2911 which is individual to the selected marker, is operated by means of a circuit from ground through the back contact of relay 2912, right winding of relay 2911, conductor 2922, inner right contact of ¹⁰⁵ relay 2805, conductor 2814, contact of relay 2411, right contact of relay 2402, and thence to battery over conductor 2718 as previously traced. Relay 2911 locks through its left winding to ground in series with the winding of relay 2912 and relay 2912 also operates. Multi-contact relay 2913 is operated next in a circuit through contacts of relays ¹¹⁰ 2911 and 2912. Relay 2913 connects the various conductors from the marker to the common grid wires of the trunk connector 2902. ¹¹⁵

The next step is to operate the particular one of the multi-contact relays 2915, 2916, etc., which represents the group of ¹²⁰ trunks to which the marker is to be connected. In the present case, the group of trunks appearing in the vertical row 403 of the district selectors, and comprising 70 trunks is represented by the relay 2916 and this relay is operated directly from a contact of the routing relay 2805 in the marker. The circuit therefor may be traced from battery through the winding of relay 2916, conductor 2923, outer right contact of relay ¹²⁵ 2916, ¹³⁰

2805, conductor 2815, to ground through contacts of relays 2911 and 2912. Relay 2916 connects the grid wires of the connector 2902 to the conductors leading to the test conductors of the several trunks in the proper group.

In case the trunk group outgoing from the district selector switches comprises only twenty trunks, the routing relay will cause 10 the operation of the corresponding one of a number of relays 2917, 2918, etc., which are related to the relay 2916. Any one of these relays will cause the operation of relay 2916 and will also render effective a corresponding 15 group of twenty of the series of testing relays 2400 for the purpose of testing the group of twenty trunks on the district frames. By making the proper connections on the distributing frame 2924 as indicated, 20 one or more of the relays 2917, 2918, etc., when operated, may serve to render effective one or more sections of the testing relays 2400 for the purpose of testing the corresponding groups of trunks at the district 25 frames.

Since the multi-contact relay 2916 is individual to row of contacts 403, its operation may be made to cause the operation of the vertical magnet 412. The circuit for 30 this purpose may be followed from ground, through the contact of relay 2916, thence through a contact of relay 2913, conductor 2925, right contact of relay 2403, conductor 2434, middle right contact of relay 2805, 35 conductor 2816 through the frame connector 2900, thence through the winding on magnet 412 to battery. Magnet 412 prepares the contacts in the vertical row 403 and also operates relay 2406 in the marker. The 40 circuit for relay 2406 may be completed from ground, through the contact of magnet 412, conductor 419, through the frame connector 2900, conductor 2927, winding of relay 2406 to battery. Relay 2406 locks through its 45 inner right contact to the grounded conductor 2520.

The marker has thus been connected to the district frame and the trunk group outgoing therefrom and the apparatus is now 50 in condition to test the horizontal links in the district switch and the corresponding outgoing trunks. Assuming the first horizontal link 406 to be busy, a ground potential will exist on the sleeve conductor thereof and testing relay 2420 operates in a circuit from battery, through its right winding, middle contact of relay 2421, thence through the frame connector 2900, conductor 420 to the grounded sleeve conductor of the 55 busy horizontal link 406. Should the first and corresponding outgoing trunk 421 also be busy, a circuit is closed from battery, through the left winding of relay 2420, inner back contact of relay 2421, thence 60 through the trunk connector 2902, conductor 65

2928, to the grounded sleeve conductor of the busy trunk 421. Relay 2420 operates as a result of either or both of its windings being energized. Similarly, if either the horizontal link 407 or the corresponding 70 trunk 422 is busy, or both are busy, the next testing relay 2422 is operated.

Assuming, however, that the link 408 and trunk 417 are both idle at the time, the testing relay 2424 remains inert. The relay 75 2425 is now operated in a circuit from battery through the winding thereof, left back contact of relay 2424, left front contacts of relays 2422 and 2420 in series, conductor 2425, through the trunk connector 2902, and 80 the distributing frame 2924 and returning through the trunk connector to conductor 2929, outer right contact of relay 2406, left back contact of slow relay 2402, to the grounded conductor 2520. Relay 2425 opens 85 the operating circuits of relay 2424 to prevent an accidental operation of this relay. The horizontal operating magnet 416 is now operated in a circuit from battery, through the right hand winding of said magnet, conductor 424, through the connector 2900, conductor 2930, to ground at the outer contact of relay 2425. Magnet 416 effects the connection through the district switch 400, thereby extending the trunk 216 to the selected 90 idle outgoing trunk 417.

Disconnection of the outgoing marker from the district frame and trunk group.—The connection having been established, the outgoing marker may be disconnected by releasing the frame connector 2900 and the trunk connector 2902. First, however, a test is made which involves contact points on the district selector switch 400 to make sure that the same has properly operated before the marker releases. For this purpose, a circuit is closed from battery, through the winding of relay 2404, left back contact of relay 2405, thence through the inner front contact of relay 2425, conductor 2437, through the trunk connector 2902, conductor 2931, through contacts of the switch 400, sleeve conductor 224 of trunk 216 to the grounded conductor 311. Relay 2404 locks and closes obvious circuits for operating relays 2402 and 2403. Relay 403 at its right contact, opens the circuit of the vertical magnet 412, which releases. At its left contact, relay 2403 opens the holding circuits of the operated test relays in the marker, and also opens the holding circuits of vertical magnet 410 and multi-contact relay 2909. 115

Relay 2402 releases the relays 2911 and 2912, which in turn causes the release of relay 2913. Relay 2402 also releases relay 2425, which opens the operating circuit of magnet 416. 120

Relay 2401 also opens the circuit of relays 2904 and 2905, in turn causing the release of relay 2906. 130

Relay 2911 in releasing releases the multi-contact relay 2916. Thus the outgoing marker has been disconnected from the district frame 400 by the release of frame connector 2900 and from the group of trunks by the release of the trunk connector 2902.

The connection through the district selector frame 400 is now held by the maintained operation of horizontal magnet 416 10 which is locked in a circuit from battery through both its windings in series, thence through contacts of the switch 400 to the grounded conductor 224.

Sending class information from the outgoing marker to the sender.—During the time the outgoing marker is connected to the sender, it transmits to said sender the necessary class information to enable the sender to proceed with the further control of the 20 equipment in extending the call. This class information is obtained from the office code which is translated in the marker and reproduced by the operation of the routing relays 2800. In the present instance, the call 25 being of the local class, the class information to this effect is given the sender by virtue of the fact that the routing relay 2805 is in operated condition.

Inasmuch as the incoming selectors 800 30 are divided into two groups, each group receiving one-half the trunks of a full group outgoing from the district frames 400, it will be necessary later on to determine with which one of these groups the incoming 35 marker should make connection. The routing relay 2805 identifies the particular group of incoming frames to which the selected trunk 417 leads. Therefore, this relay is in a position to give the sender an indication as 40 to the group of incoming frames involved, and thereafter the sender can again transfer the indication to the incoming marker at the proper time. To accomplish this end, the class relay 1602 in the sender is operated 45 by means of a circuit which may be traced from battery through the winding of said relay, conductor 1603, through the sender connector 2200, conductor 2521, through the distributing frame 2813 to ground at the inner left contact of relay 2805. Relay 1602 locks to the grounded conductor 1519.

Release of the outgoing marker from the sender.—The outgoing marker may now be disconnected since it has completed its function in setting the district selector switch 400. When relay 2402 energizes, it causes the operation of relay 1508 in the sender, by means of a circuit traceable from ground over conductor 2520, left front contact of 50 relay 2402, contact of relay 2438, conductor 2439, back contact of relay 2600, conductor 2601, through the sender connector 2200, conductor 2218, winding of relay 1508 to battery. Relay 1508 locks in a circuit traceable through the normal contact of relay 55

1517 to the grounded conductor 1519. Relay 1508 releases the relay 1509, which in turn releases relays 2207 and 2208.

Relay 2207 releases relays 2215 and 2216, and also the multi-contact relays 2201 and 70 2206. Thus, the outgoing marker is disconnected from the sender and is available for use in connection with the same or another one of the senders.

When relay 1509 releases, it releases the 75 relay 2708, which in turn, causes the de-energization of the various energized relays in the marker.

The class relay 1602 in the sender causes the operation of the skip stations relay 1604 80 in a circuit from ground through the middle right contact of relay 1602 thence through the right winding of relay 1604 to battery. Relay 1604 serves as will be later seen, to erase the effect of the stations register 2104. 85

Connection of the sender to the incoming marker.—The next step in the operation is to connect the sender through the sender-connector 3100, 3200 to an idle incoming marker for the purpose of controlling the 90 selective operation of the incoming selector switch 800 and the connector switch 1000 to complete the call. When relay 1508 operates, it causes the operation of the relay 1600 in a circuit from battery, through the 95 winding of relay 1600, left contact of relay 1602, outer left contact of relay 1605, outer right contact of relay 1517, conductor 1606, right contact of relay 2007, conductor 2008, left front contact of relay 1508, outer 100 left contact of relay 1517, to ground over conductor 1518, as hereinbefore traced. It will be noted that this circuit depends upon the energized condition of relay 2007, which operates as soon as the units digit has been received on the register 2103. Relay 1600 therefore becomes energized as soon as the sender is disconnected from the outgoing marker provided the units digit has been transmitted by the calling subscriber. 110

The relay 1600 causes the operation of relay 3106 which is individual to the sender shown at the section 3100 of the sender-connector. The circuit for this purpose may be traced from battery, through the outer contact of relay 1600, conductor 1607, thence to conductor 1607, Fig. 31, upper winding of relay 3106, right contact of relay 3108 to ground at the lower back contact of relay 3107. 115

It will be noted that several of the conductors leading from Fig. 21 have been bracketed and carried to Fig. 31 by the convention illustrated for the purpose of conserving space in the drawing. 120

Relay 3106 locks through its lower winding and the winding of relay 3107, causing the latter relay to operate. Relay 3106 operates the multi-contact relay 3101 and also initiates operation of controlling relays 125 130

3109, 3110, 3111, etc., of the connecting device in the manner explained in connection with the sender-connector shown in Fig. 22 to associate the sender with the first idle incoming marker. It will be assumed that the incoming marker shown in full is the first idle one and that the corresponding multi-contact 3105 shown in Fig. 31 is operated accordingly.

- 10 When a sender is connected to the marker, the marker start relay 3605 operates in a circuit traceable from ground through the winding of this relay, conductor 3610 through the sender-connector 3100 thence over conductor 1607 to battery at the contact of relay 1600.

Transferring the numerical record from the sender to the incoming marker.—Now that the sender has been connected to the incoming marker, the record of the thousands, hundreds, tens and units digits stored on the registers 2100, 2101, 2102, and 2103 in the sender is transferred and stored on the corresponding registers 3401, 3402, 3403 and 3404 in the marker. Relay 3605 in operating, closes the circuit for operating all of the relays of the marker registers. This circuit has several branches and may be traced as follows: Ground, through the outer right contact of relay 3605, back contact of relay 3608, conductor 3611, through the sender-connector 3100, conductor 3112, thence to conductor 3112 in Fig. 21, through the inner right back contacts of relays 2106, 2108, 2109, 2114, 2115, 2116, 2130, 2118, 2120, 2121, 2122, and thence over conductors 2125, 2126, 2127 and 2128, through the connector 3100, windings of the respective relays of the registers 3401, 3402, 3403, and 3404 to battery. These relays operate and a series circuit is completed from ground through the left contact of relay 3420, thence through the left contacts of the remaining relays of the registers, conductor 3421, winding of relay 3606 to battery. Relay 3606 locks to ground at the contact of relay 3605. The operation of relay 3606 serves as a test showing that the contacts of the connecting device 3100 are in proper condition. Relay 3606 operates relay 3608, which in turn, operates relay 3609. Relay 3608 opens the parallel circuits above traced and permits all of the relays of the marker registers to release, excepting those relays which correspond to the operated relays of the registers in the sender. In other words, relays 3406, 3407, 3408, 3411, 3412, 3413, 3414, 3416, 3417, 3418 and 3419, release, whereas relays 3405, 3409, 3410, 3415 and 3420 remain operated. The holding circuits for these latter relays may be traced from battery through their windings, thence to the sender through the inner right front contacts of the operated relays 2107, 2111, 2112, 2117 and 2123 to ground.

The indication recorded by the relay 1602 in the sender, showing to which group of incoming selectors frames the trunk 417 extends is also transferred from the sender to the incoming marker. This transfer consists in operating relay 3313 by means of a circuit traceable from battery, through the winding of said relay, conductor 3318, through the sender-connector 3100, thence to conductor 1608, Fig. 21 to ground at the right outer front contact of relay 1602.

Connection of the incoming marker to the final translator.—The next thing to happen is the selection of a proper one of the translators which serves the group of lines containing the line wanted for this call.

This selection takes place by means of the numerical registers shown in Fig. 34. Since the relays 3409 and 3410 of the hundreds

register 3402 are operated, relay 3603 is operated in a circuit from battery, through the winding of said latter relay, thence over conductor 3612, middle right front contact of relay 3409, inner left front contact of relay 3410, outer right back contact of relay 3411, inner right contact of relay 3412, conductor 3422, contact of relay 3609, conductor 3613, left back contact of relay 3319, left back contact of relay 3320, right back contact of relay 3322, conductor 3323 to ground at the inner right front contact of relay 3605.

With relay 3603 operated and register relay 3405 operated, a selecting circuit is completed for operating the relay 3802, individual to the incoming marker shown, at the connecting device 3800 which reaches the desired final translator.

This circuit may be traced from battery, through the inner left contact of relay 3605, conductor 3614, left contact of relay 3322, conductor 3324, outer right contact of relay 3606, conductor 3615, inner right contact of relay 3408, outer right back contact of relay 3407, left normal contact of relay 3406, outer

right front contact of relay 3405, conductor 3423, lowermost contact of relay 3603, conductor 3616, right winding of relay 3802, back contact of relay 3803 to ground. Relay 3802 operates and locks through its left

winding and the back contacts of relays 3807 and 3808 and the winding of the relay 3803 to ground. Relay 3803 also operates to prevent interference by the subsequent operation of relays 3807, 3808, etc., individual to other numerical registers.

With relays 3802 and 3803 operated, circuits are completed for operating the multi-contact relays 3804, 3904, and 3909. These circuits may be traced from battery, through the windings of relays 3909, 3904 and 3804 in parallel through the outer right contact of relay 3802 to ground at the front contact of relay 3803.

The connecting relay 3804 extends the various leads from the incoming marker through to the final translator 4000.

Immediately that the marker is connected to the translator, relay 4015 is operated in a circuit from battery, over the conductor 4011 through the connecting device 3800, conductor 3612, through contacts of register relays 3402 to ground over conductor 3422 as above traced. Relay 4015 operates relay 4006 in a circuit from ground through the winding of relay 4006, conductor 3809, 10 vice 3800, conductor 3617, front contact of relay 3420, and thence over conductor 3424 to battery at relay 3605 as above traced.

It will be noted that the relays of the final translator 4000 occur in pairs, relays 15 4006 and 4007 constitute one pair, relays 4004 and 4005 another pair, relays 4002 and 4003 another pair, etc. Each relay of a pair represents five of the units digits and the other relay represents the remaining five 20 units digits. The relay 4006 was operated for the reason that register relay 3420 in the marker was operated. Had this relay 3420 been deenergized, the other relay of the pair 4007 is operated instead, indicating that 25 the units digit of the wanted line occurs in the other half of the units digits.

The apparatus is now in condition to select a vertical operating magnet on a final connector frame, which controls the vertical 30 row of contacts in which appear the five called subscribers' lines containing the line wanted for this particular call. Therefore, the vertical magnet 1106 is operated in a circuit traceable from battery, through the 35 winding of said magnet, conductor 1017, lower inner contact of relay 4006, conductor 4012, through the connector device 3800, conductor 3811, through the outer right front contact of relay 3415, inner right back contact of relay 3416, conductor 3425, outer right back contact of relay 3325, conductor 3321, conductor 3326, right back contact of relay 3322, thence to the grounded conductor 3323. Magnet 1106 prepares the contacts 40 in the vertical row 1101 and also closes the circuit for operating the relay 4010. This circuit may be traced from ground through the contact of magnet 1106, conductor 1018, winding of relay 4010 to battery. The relay 4010 is individual to the connector frame 45 1000 and serves to connect the horizontal operating and testing leads through to the incoming marker. Relay 4009 is individual to a second one of the final connectors of the 50 same group and serves for a similar purpose.

Connection of the incoming marker to the incoming selector frame.—When the incoming marker is connected to the final 55 translator, the connecting device 3800 causes the operation of relay 3315 which initiates the operation of the incoming frame connector 3700. The circuit for relay 3315 may be traced from battery, through the winding of said relay, conductor 3327,

contacts of relays 3802 and 3803 to ground. Relay 3315 locks through its right contact to the grounded conductor 3323. Since the frame test relay 3313 is operated, indicating in which group of incoming frames the frame 70 800 occurs, a circuit is completed for relay 3702 of the frame connector 3700. Had the relay 3314 been operated, the frame connector 3701 would be employed to connect the marker to a second group of 75 incoming frames. The circuit for relay 3702 may be traced from battery at the left inner armature of relay 3605, conductor 3614, left contact of relay 3322, left contact of relay 3315, contact of relay 3313, right 80 winding of relay 3702 to ground at the contact of relay 3703. Relay 3702 operates and locks through its left winding, back contacts of other relays such as relay 3709, winding of relay 3703 to ground. Relay 85 3703 operates in this circuit and opens the operating circuits of the other relays similar to 3702, individual to other incoming markers. The multi-contact relay 3704 is now operated in a circuit through the front 90 contacts of relays 3702 and 3703.

The incoming frame connector 3700 when taken for use, completes a circuit for operating the vertical magnet 808 controlling the vertical row of contacts 802 on the incoming selector in which appears the trunk 417 over which the calling line has been extended. This circuit may be traced from ground through the front contacts of relays 3703 and 3702 thence over conductor 3710, 100 left contact of relay 3317, conductor 3328, through the sender-connector 3100, conductor 3113, thence to conductor 3113, Fig. 21, conductor 1523, conductor 1230, through the sender selector switch 1200 to conductor 105 316, thence over the tip of trunk 216 through the district selector switch 400, over the tip of trunk 417, through the upper front contact of relay 706, left winding of relay 701 to battery. It will be noted that relay 706 is operated in a circuit from battery, through its winding and the back contact of relay 700 to ground on the sleeve conductor 425 of trunk 417. Relay 701 operates the vertical magnet 808 in a circuit 110 from ground through the middle right contact of relay 701, middle contact of relay 702, conductor 712, winding of magnet 808 to battery. Relay 701 also operates the multi-contact relay 3708. This circuit may 115 be traced from ground through the outer right contact of relay 701, right outer contact of relay 702, conductor 713, winding of relay 3708 to battery. With relays 3704 and 3708 operated, the leads from the incoming marker are extended through the frame connector 3700 to the incoming frame 120 800.

The relay 3708 is individual to the horizontal section 814 of the incoming selector 125 130

switch 800 and serves not only to extend the leads from the incoming marker to the frame 800, but to extend them only to this particular horizontal section 814. The reason for this is that the incoming trunk 417 over which the connection has been extended appears only in the section 814 and therefore, the marker is not interested in the remaining sections of the switch. Another relay 3707 of the frame connector is seen to be individual to the section 813 of the incoming selector 800. In a similar manner, still other relays are provided for other sections in the same and in other incoming selectors of the same group.

Magnet 808 of the incoming frame operates and prepares the contacts in the vertical row 802 and locks in a circuit through its winding and contact, thence through the frame connector 3700, conductor 3711, to the grounded conductor 3321. Multi-contact relay 3708 also locks in a circuit traceable through the frame connector 3700 to ground over conductor 3711.

The vertical magnet 812 which controls the row of contacts 806 in which appear the trunks of the group 824 leading to the proper group of idle connector switches, is now operated. The circuit for this magnet may be traced from battery, through the winding thereof, thence through the frame connector 3700, conductor 3712, contact of relay 3909 to ground on the grid wire. The magnet 812 is selected by the connecting device 3901 which constitutes a part of the final translator. The final translator being individual to the desired group of lines and consequently to the group of final connectors reaching these lines, selects the vertical magnet 812 as the one on the frame which controls the group of trunks reaching the said group of connector switches.

Inasmuch as a total group of trunks leading from the incoming selectors to the final selectors of a particular group may be more than can be allotted to a single vertical row of contacts in the incoming switches, it is necessary to split the total group into two or more subgroups and divide each subgroup among a portion of the incoming selector switches. Accordingly, it is necessary to ascertain which subgroup of trunks is involved before the incoming marker should be connected thereto. Assume, therefore, that the group of trunks 824 is one subgroup of a total group. It is necessary to operate the proper one of the multi-contact relays 3911, 3912, etc., in the device 3901, in order to connect the marker to this particular subgroup 824 instead of some other subgroup. As will be seen by inspection, the relay 3911 is individual to the subgroup 824 and this relay is operated in a circuit from battery through its winding, contact

of relay 3909, thence through contacts of relays 3704 and 3708 to ground. The relays 3707, 3708, etc. have one of their contacts arbitrarily grounded in such a manner that when any one of these relays relating to the incoming selectors on which a subgroup of trunks 824 in multiple is operated, the particular one of the relays 3911, 3912, etc., which connects the marker to that particular subgroup of trunks will also be operated.

Testing the horizontal links of the incoming and connector switches and the interconnecting trunks.—Inasmuch as the testing operation concerns the final connector switch, it is necessary to associate the marker testing relays 3300 with the horizontal section 1016 of the connector switch 1000. This is accomplished by operating the relay 3907 in a circuit from battery through the winding thereof, conductor 3812, through the device 3800, conductor 3813, inner back contact of relay 3417, back contact of relay 3418, back contact of relay 3419, conductor 3426, inner back contact of relay 3325, to the grounded conductor 3321. The relay 3907 is individual to the section 1016 in which the called line 1100 appears, and therefore, this relay is the one operated. Relays 3906, 3908, etc., are individual to other horizontal sections, representing other units digits in the connector switch 1000.

The marker has now made all necessary connections and is ready to test the incoming and final selector horizontal links and the trunks interconnecting these selector switches. For the purpose of explaining the testing equipment, it will be assumed that the horizontal link 1008 of the connector switch, the interconnecting trunk 828 and the horizontal link 819 of the incoming selector switch are simultaneously busy and that the remaining links and trunks shown are idle at the time the test is made. Since the link 1008 is busy, both the trunks 826 and 827 which appear before this link in the section 1016, must be rendered non-selectable or artificially busy because neither of them can be employed to extend the connection. This is accomplished by operating the relay 3303 of the testing mechanism 3300. The operating circuit may be traced from battery, through the winding of said relay, right contact of relay 3306, conductor 3329, through the device 3900, contact of relay 3907, conductor 4013, through the device 4001, conductor 1019, to the grounded sleeve conductor of link 1008. Relay 3303 operates both relays 3301 and 3302 in circuits through the left windings of these relays and contacts of relay 3303 to the grounded conductor 3321. Relays 3301 and 3302 represent, respectively, the trunks 826 and 827 and the horizontal links 817 and 818 and accordingly these links and trunks are rendered non-selectable.

Since it is assumed that the trunk 828 is busy, relay 3307 pertaining to this trunk is operated in a circuit from battery, through the left winding of said relay, inner 5 right back contact of relay 3310, conductor 3330, through the connecting device 3901, conductor 903, to the grounded sleeve conductor of the busy trunk 828.

Since the horizontal link 819 in the incoming switch 800 is busy, a circuit is closed from battery, through the right winding of test relay 3307, middle right contact of relay 3310, conductor 3331, through the frame connector 3700, conductor 830, to the grounded 10 sleeve conductor of link 819. Each of the double multi-test relays 3301, 3302, 3307, 3308, etc., operates when either winding is energized or when both windings are energized. Under the conditions assumed, 15 therefore, relays 3301, 3302, and 3307 operate and indicate that the first available path through the selector and connector switch leads over the horizontal link 820 of the incoming selector, trunk 829 and horizontal link 1009 of the connector switch. 20

For the purposes of the call under consideration, however, it will be assumed that the link 817 of the incoming switch, trunk 826 and link 1008 of the connector switch 25 are all simultaneously idle. Test relays 3301 and 3303 remain deenergized.

At the time the vertical magnet 812 of the incoming selector operates, a circuit is closed from ground through the contact of this magnet, conductor 831, through the connector 3700, conductor 3713, windings of 30 relays 3316 and 3317 in parallel to battery.

During the time the test is being made of the horizontal links and trunks, a test of the called subscriber's line is also taking place. When the final translator is connected to the connector switch 1000 through the connecting device 4001, the magnet 1020 which controls the testing link 1010 common to the 40 connecting links of the section 1016, is operated. The circuit for this purpose may be traced from battery, through the right winding of said magnet, conductor 1021, through the connecting device 4001, through the connecting device 3900, conductor 3913, to the grounded conductor 3321. Magnet 1020 operates and prepares to test the condition of the called line 1100 over the testing link 1010. 50

The test circuit extends from battery, through the left winding of test relay 3332, conductor 3333, through the connector 3901, through the connector 4001, conductor 1022, over the lower conductor of test link 1010 to the sleeve conductor of the called line 1100. Assuming the called line to be idle at this time, the test relay 3332 remains deenergized. The horizontal magnet 1020 in operating, operates the relay 3334 in the marker, in a circuit traceable from battery, 55

through the winding of said relay, conductor 3335, through the connectors 3901, and 4001, conductor 1023, to ground at the contact of magnet 1020. With relays 3316 and 3334 operated, a circuit is closed for operating relay 3304. This circuit may be traced from battery, through the winding of said relay, left back contact of relay 3301, conductor 3336, outer right contact of relay 3334, to ground at the inner contact of relay 3316. Relay 3304 operates the relay 3306 in an obvious circuit. 70

Relay 3304 identifies the idle trunk 826 whose idle condition has been ascertained and accordingly completes a circuit for 80 operating the vertical magnet 1011 in the connector switch which controls the vertical row of contacts 1001 in which appears the said trunk 826. The circuit for operating the magnet 1011 may be traced from the 85 grounded conductor 3321, outer left contact of relay 3304, conductor 3337, thence through the connecting devices 3901 and 4001, winding of magnet 1011 to battery. Relay 3304 at its inner right contacts, opens 90 the operating circuits of relay 3301 to prevent this relay from subsequently operating. Such other of the testing relays 3302, 3309, etc., as are operated, at the time, lock in circuits leading through their left windings and locking contacts, thence over conductor 3338, inner right contact of relay 3334 to ground at the outer contact of relay 3316. By locking these relays, they are prevented from releasing in case the trunk or 95 link becomes idle to disrupt the extended start circuit that leads through the successive contacts. 100

When the vertical magnet 1011 of the connector switch energizes, it operates the relay 105 3339 in a circuit traceable from battery, through the winding of said relay, conductor 3340, thence through the connecting devices 3901 and 4001 to ground at the contact of magnet 1011. Relay 3339 operates 110 the horizontal magnet 821 of the incoming selector 800 and the horizontal magnet 1024 of the connector switch 1000. The circuit for magnet 821 may be traced from battery, through the right winding of said magnet, conductor 832, through the frame connector 3700, conductor 3714, outer right contact of relay 3304, conductor 3341, left contact of relay 3339 to the grounded conductor 3321. Magnet 821 operates and rotates the associated horizontal rod and extends the trunk 417 over link 817 to the idle trunk 826. The circuit for operating magnet 1024 may be traced from battery, through the right winding thereof, conductor 1025, through the connecting devices 4001 and 3900, conductor 3715, left contact of relay 3306, to the grounded conductor 3341. Magnet 1024 rotates the associated rod and effects connection from the trunk 826 through the horizontal 115 rod 120 to the marker 125 in the testing link 1010. Magnet 1024 rotates the associated rod and effects connection from the trunk 826 through the horizontal rod 130 to the marker 135 in the testing link 1010.

zontal link 1008 to the called subscriber's line 1100. As soon as the connection is effected, the busy test relay 3332 is operated in a circuit through its left winding and thence over conductor 3333 as above traced to the lower conductor of the test horizontal link 1010 to the sleeve conductor 1026 of the called line, thence to the sleeve conductor of the horizontal link 1008, thence over conductor 1019 as above traced to ground. Relay 3332 operates and locks through its right winding to the grounded conductor 3321. During this time, the release relay 3342 is also operated. The circuit for this relay may be traced from battery, through its winding, conductor 3343, inner right front contact of relay 3304, conductor 3344, through the connector device 3901, conductor 904, sleeve conductor 833 of the trunk 826, thence through contacts of switch 800 to ground over conductor 1019 as previously traced.

Release of the incoming marker and the translator.—The connection having been completely established through the incoming selector switch, the marker and translator may be discharged. With relays 3332 and 3342 operated jointly, relay 3346 is operated in a circuit from battery through the right winding of said relay, contact of relay 3342, outer front contact of relay 3332, to the grounded conductor 3321. Relay 3346 locks through its left winding and contact to the grounded conductor 3323. Relay 3346 operates the relay 3322. This latter relay in operating, opens the holding circuits upon which relays 3702, 3708, 3802, 3904, 3909, 4006 and 3315 depend. These relays release whereby the incoming marker is disconnected from the incoming frame and from the final translator and these mechanisms are discharged. The holding circuits of the vertical operating magnets 808, 812, 1011 and 1016 are also open when the marker and translator are released. These magnets deenergize to restore the unused contacts in their associated rows. The connection through the switches is held by the continued energization of the horizontal magnets net over circuits which will be discussed hereinafter.

Disconnection of the incoming marker from the register sender.—The marker is also disconnected from the sender by releasing the sender connector 3100. To accomplish this, a notification is transmitted from the marker to the sender informing it that disconnection should take place and the sender thereupon proceeds to release the sender-connector 3100. When relay 3322 operates, a circuit is established from the grounded conductor 3323, through the right front contact of relay 3322, thence over the conductor 3347, right back contact of relay 3500, conductor 3501, through the connector

3100, conductor 3114, thence to conductor 3114 (Fig. 21), winding of relay 1605 to battery. Relay 1605 locks through its right contact and contact of relay 1517 to the grounded conductor 1519. Relay 1605, at its right contact, opens the holding circuit of relay 1600 which releases and opens the circuit of relays 3106 and 3107 of the sender-connector 3100. These latter relays release and bring about the release of the sender-connector 3100 whereby the sender is disconnected from the incoming marker.

The release of the sender-connector 3100 releases relay 3605, the energized relays depending upon this relay, together with the operated relays of the marker registers, and the translating device 3600 also release.

Release of the register sender.—When relay 1605 operates, it operates the sender release relay 1524 in a circuit traceable from battery, through the winding of relay 1524, left contact of relay 1514, conductor 1525 to ground at the inner left contact of relay 1605. Relay 1524 locks through its inner right contact to ground on conductor 1519. Relay 1524 at its right normal contact, opens the holding circuit of relay 1505 which releases and causes the release of holding relay 1504. Relay 1504 removes ground potential from the various holding conductors permitting the energized relays in the sender and register to become deenergized including the sender release relay 1524. During the interval the sender is releasing relay 1524 at its outer right front contact maintains the circuit for the right winding of relay 1224, to render this sender non-selectable to the sender-selector switches until it has become fully released.

The operation of relay 1524 removes ground potential from the holding conductor 1511, whereby the horizontal operating magnet 1220 and the relay 1304 and relay 1219 become released. Thus, the sender selector switch 1200 is released and the sender is disengaged from the calling subscriber's line.

When the sender releases, it removes ground from conductor 314 causing the release of relays 300, 306 and 315. Relay 300 extends the tip and ring conductors of the calling line through to the repeating coil 302 causing the operation of relay 304. Relay 306 at its right contact removes ground from conductor 311, and relay 305 still maintains ground on the holding conductor 311 closed through its inner upper contact. Relay 305 applies ground from its inner upper contact to conductor 311, whereby the line switch 200 and the selector switches are held in their operated condition.

Application of ringing current to the called line.—Referring back to where the incoming selector 800 and the connector switch 1000 are operated and the marker is

released, a description will now be given of the manner in which these switches are held prior to describing the application of ringing current to the called line.

- 5 The horizontal magnet 821 of the incoming selector in operating, locks in a circuit from battery, through both its windings, thence through contacts of the switch 800, to the sleeve conductor 426 of the trunk 10 417, winding of relay 700, to ground on the sleeve conductor 425. Magnet 821 holds and relay 700 operates in this circuit.

The relay 900 in the trunk circuit 826 also operates over a path traceable from battery, 15 through the winding of said relay, sleeve conductor 905, through contacts of the switch 800 to ground on the sleeve conductor 826. Relay 900 closes a holding circuit for the horizontal magnet 1024, traceable from battery, through both windings of said magnet, thence through contacts of the switch 1000, conductor 833 to ground at the inner 20 right front contact of relay 900. Relay 900 also operates the relay 902 in an obvious circuit. Relay 902 which is slow to release affords a substitute path for applying ground potential to the sleeve conductor 833.

Relay 700 releases the relay 706 which 30 in turn releases relay 701. Relay 700 operates the ringing relay 704 in a circuit from battery, through the winding of relay 704, inner lower contact of relay 708, contact of ringing trip relay 703, front contact of relay 700 to the grounded conductor 425. Immediately that relay 704 operates, ringing current is applied to the called line in a circuit traceable from the ringing source 709, left back contact of relay 701, winding of relay 703, inner left contact of relay 704, lower back contact of relay 708, thence over the ring side of the line through the called subscriber's station and returning over the tip side of the line through the 40 uppermost contact of relay 708 to ground at the left contact of relay 704. Relay 703 being marginal, does not operate in series with the resistance at the called sub-station.

Relay 700 closes a circuit from battery, 50 through the winding of relay 708, to the grounded conductor 425. Relay 708, however, does not operate since it is shunted by a circuit from battery, through the inner upper contact of said relay, inner lower contact thereof, contact of relay 703, through the contact of relay 700 to the grounded conductor 425. As soon as the continuously operating interrupter 711 closes its lower contact, after relay 704 operates, a circuit 55 is closed from ground through the lower contact of said interrupter, right contact of relay 704, contact and winding of relay 702 to battery. Relay 702 operates and locks and on the next closure of the upper contact of interrupter 711, and relay 701 is op-

erated in a circuit from battery, through the right winding and locking contact thereof, inner left contact of relay 702, upper contact of interrupter 711, to ground. Relay 701 locks through its right winding and 70 inner right front contact, thus disconnecting the immediate ringing source 709. Interrupted ringing current is now applied from the source 710 through the left outer contact of relay 702, left front contact of 75 relay 701, thence as above described over the called subscriber's line and returning to ground at the contact of relay 704.

When the called subscriber answers by removing his receiver from the switchhook, 80 the resistance of the loop is reduced in the well known manner and relay 703 operates. Relay 703 removes the shunt and permits relay 708 to operate. Relay 708 disconnects ringing current and completes the tip and 85 ring conductors from the called line through to the repeating coil 707 causing relay 705 to operate. Relays 701, 704, 702 and 703 thereupon release.

Relay 705 in operating, operates the relay 90 303 in the district trunk circuit by means of a circuit traceable from battery, through the lower left winding of repeating coil 707, contact of relay 706, thence over the ring side of the trunk through the district selector switch 400, lower right winding of repeating coil 302, winding of relay 303, upper right winding of repeating coil 302, upper contact of relay 305, upper back contact of relay 300 thence over the tip side of the 100 trunk, through the district selector, upper back contact of relay 706, upper left winding of repeating coil 707 to ground at the contact of relay 705. As soon after relay 303 operates, as interrupter 318 closes its 105 lower contact, a circuit is completed from battery, through the lower contact of said interrupter, normal contacts and right winding of relay 319, right middle contact of relay 315, to ground at the front contact 110 of relay 303. Relay 319 operates and locks through its right winding. As soon thereafter as the interrupter 318 closes its upper contact, a period later, relay 315 operates in a circuit from battery through the upper 115 contact of said interrupter, inner right contact of relay 319, right winding of relay 315 to ground. Relay 315 locks through its left hand winding and releases the relay 319.

The talking connection has been established and conversation may now take place.

Release of the established connection.—After the conversation has been completed, the calling and called subscribers replace their receivers on the switchhooks. The calling subscriber by replacing his receiver, causes the release of relay 304. As soon thereafter as interrupter 313 closes its lower contact, relay 312 is operated by means of a circuit from battery, through the lower con- 120 125 130

part of said interrupter, normal contact and left winding of relay 312, contact of relay 304, middle lower contact of relay 305, to ground at the right back contact of relay 306. 5 of ground from this conductor releases the 65 connector switch 1000.

Called subscriber's line tests busy.—It will be considered that the called subscriber's line 1100 is already engaged at the time the marker makes a test thereof. This being the 70 case, the ground potential exists on the sleeve conductor 1026 and the test relay 3332 operates in the circuit hereinbefore traced. Relay 3332 locks through its right winding and contact to the grounded conductor 3321. 75 Since the relay 3339 has not operated at this time, relay 3332 causes the operation of relays 3320 and 3348. The circuit for this purpose may be traced from battery, through 80 the windings of relays 3320 and 3348 in parallel, right contact of relay 3339, left front contact of relay 3332, to the grounded conductor 3321. Relay 3320 opens the circuit of relay 3603 which in turn brings about the release of the final translator from the incoming marker. In this manner, the connector switch 1000 is disconnected from the incoming marker and the test relays in the marker which are operated, due to the busy condition 85 of the horizontal links on the connector switch or trunks leading to the connector switch are released. 90

Relay 3320 operates the vertical magnet 810 on the incoming selector switch 800 which controls the row of contacts 804. This 95 row of contacts is devoted to busy tone equipment for sending a busy tone back to the calling subscriber whenever the line is found to be engaged. The circuit for magnet 810 may be traced from battery, through the winding thereof, thence through the frame connector 3700, conductor 3716, inner right contact of relay 3320, the right back contact of relay 3322, to the grounded conductor 100 3323. It may be noted that the vertical magnet 812 is released at the time the translator is disconnected from the marker in order to prevent the busy tone apparatus from being connected to the trunks leading to the connector switches. Relay 812 releases relays 105 3316 and 3317. 110

The magnet 810 in operating, completes a circuit traceable from ground through its contact, conductor 834, through the frame connector 3700, conductor 3717, right contact of relay 3317, conductor 3349, thence through the inner contact of relay 3348, conductor 3336, left back contact of relay 3301, winding of relay 3304 to battery. Another 115 circuit may be traced from ground over conductor 3349, through the outer right contact of relay 3348, thence over conductor 3341, through the outer right contact of relay 3304, conductor 3714, and thence as previously traced through the winding of horizontal magnet 821. Magnet 821 connects the busy tone device 835 to the trunk 417. Current flowing over the trunk through the 120 125

5 Relay 312 locks through its left winding and as soon as interrupter 313 closes its upper contact, relay 301 is operated. The circuit for this latter relay may be traced from battery, through the upper contact of the interrup- 10

10 rupter 313, left inner contact of relay 312, inner left back contact of relay 319, lower winding of relay 301 to ground. Relay 301 locks through its upper winding and inner upper front contact, outer left contact of relay 319, to ground at the inner right contact of relay 312. Relay 301 opens the circuit of relay 305 and this relay releases. During the period that the upper contact of interrupter 313 is closed, relay 312 is held energized in a circuit from battery, through the upper contact of said interrupter, inner left contact of relay 312 to ground through the right winding of said relay. Relay 312 during this interval, maintains ground on the sleeve conductor 311, in a circuit traceable through its inner right contact, outer left contact of relay 319, conductor 310 to conductor 311. Relay 312 also maintains ground on the conductor 222. Therefore, the connection is not immediately released upon the deenergization of relay 305. 15

When interrupter 313 opens its upper contact immediately relay 312 releases and removes ground from the holding sleeve conductors, thereupon the line switch 200 is restored, disconnecting the calling line from the trunk 216. Also, the district selector switch 400 is released and ground potential is removed from the sleeve conductor 425 of the trunk 417. The removal of ground from conductor 425 releases relay 700 and also releases the horizontal magnet 821 of the incoming selector switch 800. The trunk 417 is thereby disconnected from the trunk 905 through the release of the incoming selector 45 800. The release of relay 700 releases relay 708.

The removal of ground from the sleeve conductor 425 also releases the relay 900. As 50 soon after relay 900 releases as the interrupter 906 closes its lower contact, relay 901 is operated. The circuit for this purpose may be traced from battery, through the winding and normal contact of relay 901, outer right contact of slow release relay 902, left contact of relay 900, to ground at the lower contact of interrupter 906. Relay 901 operates and locks through its winding and contact to ground at the inner right contact 55 of relay 902. Since the called subscriber has replaced his receiver on the switchhook, relay 902 releases after an interval and releases relay 901 which removes ground potential from conductor 833. The removal

of ground from this conductor releases the 65 connector switch 1000.

Called subscriber's line tests busy.—It will be considered that the called subscriber's line 1100 is already engaged at the time the marker makes a test thereof. This being the 70 case, the ground potential exists on the sleeve conductor 1026 and the test relay 3332 operates in the circuit hereinbefore traced. Relay 3332 locks through its right winding and contact to the grounded conductor 3321. 75 Since the relay 3339 has not operated at this time, relay 3332 causes the operation of relays 3320 and 3348. The circuit for this purpose may be traced from battery, through 80 the windings of relays 3320 and 3348 in parallel, right contact of relay 3339, left front contact of relay 3332, to the grounded conductor 3321. Relay 3320 opens the circuit of relay 3603 which in turn brings about the release of the final translator from the incoming marker. In this manner, the connector switch 1000 is disconnected from the incoming marker and the test relays in the marker which are operated, due to the busy condition 85 of the horizontal links on the connector switch or trunks leading to the connector switch are released. 90

Relay 3320 operates the vertical magnet 810 on the incoming selector switch 800 which controls the row of contacts 804. This 95 row of contacts is devoted to busy tone equipment for sending a busy tone back to the calling subscriber whenever the line is found to be engaged. The circuit for magnet 810 may be traced from battery, through the winding thereof, thence through the frame connector 3700, conductor 3716, inner right contact of relay 3320, the right back contact of relay 3322, to the grounded conductor 100 3323. It may be noted that the vertical magnet 812 is released at the time the translator is disconnected from the marker in order to prevent the busy tone apparatus from being connected to the trunks leading to the connector switches. Relay 812 releases relays 105 3316 and 3317. 110

The magnet 810 in operating, completes a circuit traceable from ground through its contact, conductor 834, through the frame connector 3700, conductor 3717, right contact of relay 3317, conductor 3349, thence through the inner contact of relay 3348, conductor 3336, left back contact of relay 3301, winding of relay 3304 to battery. Another 115 circuit may be traced from ground over conductor 3349, through the outer right contact of relay 3348, thence over conductor 3341, through the outer right contact of relay 3304, conductor 3714, and thence as previously traced through the winding of horizontal magnet 821. Magnet 821 connects the busy tone device 835 to the trunk 417. Current flowing over the trunk through the 120 125

5 Relay 312 locks through its left winding and as soon as interrupter 313 closes its upper contact, relay 301 is operated. The circuit for this latter relay may be traced from battery, through the upper contact of the interrup- 10

10 rupter 313, left inner contact of relay 312, inner left back contact of relay 319, lower winding of relay 301 to ground. Relay 301 locks through its upper winding and inner upper front contact, outer left contact of relay 319, to ground at the inner right contact of relay 312. Relay 301 opens the circuit of relay 305 and this relay releases. During the period that the upper contact of interrupter 313 is closed, relay 312 is held energized in a circuit from battery, through the upper contact of said interrupter, inner left contact of relay 312 to ground through the right winding of said relay. Relay 312 during this interval, maintains ground on the sleeve conductor 311, in a circuit traceable through its inner right contact, outer left contact of relay 319, conductor 310 to conductor 311. Relay 312 also maintains ground on the conductor 222. Therefore, the connection is not immediately released upon the deenergization of relay 305. 15

When interrupter 313 opens its upper contact immediately relay 312 releases and removes ground from the holding sleeve conductors, thereupon the line switch 200 is restored, disconnecting the calling line from the trunk 216. Also, the district selector switch 400 is released and ground potential is removed from the sleeve conductor 425 of the trunk 417. The removal of ground from conductor 425 releases relay 700 and also releases the horizontal magnet 821 of the incoming selector switch 800. The trunk 417 is thereby disconnected from the trunk 905 through the release of the incoming selector 45 800. The release of relay 700 releases relay 708.

The removal of ground from the sleeve conductor 425 also releases the relay 900. As 50 soon after relay 900 releases as the interrupter 906 closes its lower contact, relay 901 is operated. The circuit for this purpose may be traced from battery, through the winding and normal contact of relay 901, outer right contact of slow release relay 902, left contact of relay 900, to ground at the lower contact of interrupter 906. Relay 901 operates and locks through its winding and contact to ground at the inner right contact 55 of relay 902. Since the called subscriber has replaced his receiver on the switchhook, relay 902 releases after an interval and releases relay 901 which removes ground potential from conductor 833. The removal

right windings of repeating coil 707, induces a tone current in the left windings of the repeating coil which current flows through the calling subscriber's receiving set producing a characteristic sound therein, notifying him that the called line is busy.

- The relay 3320 in operating, operates the relay 3350. Later, when ground is applied to conductor 3349, the relay 3351 operates, 10 opening the circuit of relay 3350. Relay 3350 being slow to release, requires an interval to retract its armature. When relay 3350 releases, slow-to-operate relay 3352 operates in an obvious circuit and locks. 15 After an interval, relay 3351 which is also slow-to-release, retracts its armatures. When relay 3351 releases, a circuit is closed from battery, through the right winding of release relay 3346, right contacts of relays 20 3351 and 3352 to ground. Relay 3346 brings about the release of the equipment in the manner described hereinbefore.

Establishment of an interoffice connection.

- 25 A description will next be given of the manner in which the equipment functions in establishing a connection from a calling subscriber's line in the local office over the district selector 400 and an office selector 30 to 600 to a trunk outgoing to a distant exchange.

Assume that the office code of the call is represented by the abbreviation letters ACA which in terms of dial impulses is represented by three series of two impulses each. Assume also that the number of the wanted line is the same as in the previous case, namely 2345. In this instance, the calling subscriber first dials three series of two impulses each, which are received in the sender as above explained and cause the operation of relays 1916, 1940 and 1941 of registers 1901, 1902 and 1903. The numerical impulses, when transmitted, cause the operation of the same numerical register relays as in the case of the call previously considered.

After the sender is associated with the outgoing marker, the office record is transferred and relays 2504, 2508 and 2512 of the marker registers are operated. By tracing the circuits through registers 2500 and 2501, it will be found that relays 2702 and 2705 of the translator 2700 are operated. 55 With these relays operated, a circuit is completed for the routing relay 2808, and may be traced from battery through the winding of said relay, conductor 2817, contact of relay 2702, contact of relay 2705, conductor 2719, middle right back contact of relay 2511, inner left front contact of relay 2512, outer right back contact of relay 2513, 60 inner right contact of relay 2514 to the grounded conductor 2517.

When the district frame connector 2900 operates, it operates relay 2811 as above described. Relays 2811 and 2808 determine the operation of relay 2806. The circuit for this purpose may be traced from ground through the outer left contact of relay 2808, 70 conductor 2819, winding of relay 2806, conductor 2820, to battery at the contact of relay 2811. Relay 2806 operates the trunk connector relay 2911 in the manner hereinbefore described. The circuit is now completed for the multi-contact relay 2915, 75 which is individual to the group of trunks appearing in the row 405 of the district switch, which lead to the office selectors, one of which is shown in Fig. 6. The circuit for this relay may be traced from battery, through the winding thereof, thence over conductor 2932, outer right contact of relay 2806, conductor 2815, to ground through contacts of relays 2911 and 2912. Relay 80 2915 operates and the outgoing marker is thus associated with the group of trunks outgoing from the district to the office selector switches.

The vertical operating magnet 413 is operated in a circuit from battery, through the winding thereof, through the frame conductor 2900, thence over conductor 3013, through the middle right contact of relay 2806, conductor 2434 and thence to ground 90 over the path previously traced at the contact of relay 2915. The magnet 413 prepares the contacts in the row 405 and operates the relay 2406 as above explained.

The horizontal links in the district selector 400 and the outgoing trunks are tested simultaneously by means of the marker testing relays. An idle pair of these is selected and the connection is established through the district selector switch in the manner 100 fully explained hereinbefore. Assume, for example, the connection is extended through the district selector 400 to the trunk 502 leading to the office selector switch 600 and appearing in the vertical row of contacts 105 602.

When the connection is effected to the district selector, relay 2404 operates and in turn operates the release relays 2402 and 2403. Relay 2402 opens the circuit of relay 115 2904 causing the release of the district frame connector 2900. This relay 2402 also releases the relay 2911 causing the release of the district trunk connector 2902. Thus, the outgoing marker is disconnected from the 120 district frame 400 and the trunks outgoing therefrom. It will be recalled that relay 2402 on the previous call sent a signal back to the sender operating the relay 1605 notifying the sender that it should release from 125 the marker. Inasmuch as the office switch must be operated in this case, this signal is prevented by the operation of relay 2438

as will be presently described. Relay 2402 is slow to operate to give relay 2438 sufficient time to energize.

The trunks leading from the district to the office frames may be arranged in two or more subgroups in case the total group is larger than a single vertical row of contacts can accommodate. In order to distinguish the particular subgroup involved, all the trunks of a given subgroup are identified by the characteristic circuit connected to the contact of relay 500, there being one of these for each trunk in the subgroup. In the present case, a low resistance 501 is connected to the back contact. For a second subgroup, the resistance 501 would be high. Immediately that the connection is established through the district selector frame 400, a circuit is closed through the windings of relays 2440 and 2441. This circuit may be traced from ground, through the low resistance 501, inner back contact of relay 500, thence over the ring side of trunk 502, through the district selector switch 400, conductor 320, through the sender selector switch 1200, conductor 1231, conductor 1526, through the sender-connector 2200, conductor 2522, outermost back contact of relay 2401, windings of relays 2440 and 2441 to battery. Since the resistance 501 is low, both the marginal relay 2440 and the relay 2441 operate. These relays lock to the grounded conductor 2520. Relay 2441 operates relay 2442, which also locks.

At the time relay 2806 operated, it caused the operation of relay 2443, in a circuit from battery through the winding of the latter relay, thence over the conductor 2444, to ground at the contact of relay 2806. Relay 2443 locks to the grounded conductor 2520. Relay 2438 is now operated in a circuit from battery, through its winding, outer left contact of relay 2443, conductor 2445, left back contact of relay 2709 to ground at the contact of relay 2708. Relay 2438 thus prevents the sender from receiving a notification to release from the district marker until after the office selector switch has been operated.

Connection of the outgoing marker to the office selector frame.—As soon as relay 2443 operates, it causes the operation of the relay 3002, individual to the marker in the office frame connector 3000. The circuit for this purpose may be traced from ground, through the back contact of relay 3003, right winding of relay 3002, conductor 3014, right contact of relay 2443, right front contact of relay 2440, left contact of relay 2442, right contact of relay 2407, to battery over conductor 2718. Relay 3002 locks in series with relay 3003 and the two jointly cause the operation of multi-contact relay 3004.

The vertical magnet 609 of the office selector switch 600 is operated due to the operation of the frame connector 3000. The cir-

cuit for operating this magnet may be traced from battery, through the winding thereof, conductor 612, outer back contact of relay 500, thence over the tip of the trunk through the district selector switch and thence over conductor 316 as previously traced, sender-connector 2200 to conductor 2519 and thence through the inner left front contact of relay 2406, left contact of relay 2401, conductor 2446, contacts of relays 3002 and 3003 to ground. Relay 2412 is also operated in parallel with the circuit above traced. The magnet 609 prepares the contacts of the vertical row 602 and also operates the multi-contact relay 3006 which is individual to the particular office selector frame 600. The circuit for this latter relay may be traced from battery, through the winding thereof, thence through the contact of magnet 609 to ground on conductor 612. The magnet 609 and relay 3006 lock in circuits, through their windings thence over a path through the office frame connector 3000, conductor 3015, through the left contact of relay 2408, left front contact of relay 2402, to the grounded conductor 2520.

Connection of the outgoing marker to the trunk group at the office selector switch.—The relay 2412 which operates when the frame connector 3000 operates, closes an energizing circuit for the relay 3007 of the office trunk connector 3001. This circuit may be traced from ground, through the back contact of relay 3008, right winding of relay 3007, conductor 3016, thence through the inner right contact of relay 2808, conductor 2821, contact of relay 2412, through the right contact of relay 2407, to battery over conductor 2718. Relay 3007 operates and locks through its left winding and the winding of relay 3008 and the latter relay also energizes. Relays 3007 and 3008 jointly operate the multi-contact relay 3009.

Assume that the group of trunks leading to the desired office appear in the vertical row 604 of the office selector switch 611, and that the relay 3017 is individual to this particular group. Relay 3017 accordingly is operated in a circuit traceable from battery, through the winding thereof, conductor 3018, through the outer right contact of relay 2808, conductor 2822, through contacts of relays 3007 and 3008 to ground. Relay 3017 operates the relay 3010, whereby the test conductors of the trunks in the outgoing group are connected through to the test relays 2400 in the marker.

The vertical operating magnet 611 is next energized by means of a circuit from battery, through its winding, thence over conductor 613, through the frame connector 3000, conductor 3019, through the middle right contact of relay 2808, thence over conductor 2823, through the right contact of relay 2408, conductor 2447, through contacts

of the trunk connector 3001 to ground. It will be noted that relay 2405 operates in parallel with the circuit just traced. The magnet 611 prepares the contacts in the vertical row 604 and also operates the relay 2401 in a circuit traceable from battery, through the winding of said relay, conductor 2448, through the frame connector 3000, to ground at the contact of magnet 611.

- 10 *Testing the horizontal links of the office switch and the outgoing trunks.*—The horizontal links 605, 606, 607, 608, etc., of the office switch 600, and the corresponding trunks of the outgoing group are tested by means of the test relays 2400 in the marker in exactly the same manner as discussed in connection with the district selector 400. Assume that the link 608 and the corresponding trunk 614 are both idle, and that no preceding trunk and its corresponding link are both idle. Accordingly, relays 2420, 2422, 2424 are all operated and relay 2426 is the first one in the series to remain deenergized. The relay 2427 is next operated in a circuit from battery, through its winding, left back contact of relay 2426, left front contacts of the preceding test relays thence over conductor 2435, thence through the office trunk connector 3001, through the inner left contact of relay 3017, and returning through a contact of the office connector over conductor 2929, outer right contact of relay 2401, left contact of relay 2407, left front contact of relay 2402 to ground on conductor 2520. Relay 2427 at its outer right contact, closes a circuit through the frame connector 3000 for the horizontal magnet 615. The magnet 615 locks through its windings and contacts of the switch 600, thence over conductor 503, through the relay 500 and the district selector switch 400 to ground on the sleeve conductor 224 of the trunk 216. Relay 500 operates and completes the tip and ring conductors of the trunk and opens the operating circuit of the vertical magnet 609.

- 50 *Release of the marker from the office selector switch.*—The connection through the office switch has thus been established and the marker may now be released. This is accomplished by operating relay 2450 in a circuit from battery, through the winding thereof, left front contact of relay 2405, conductor 2451, inner right contact of relay 2427, conductor 2452, through the trunk connector 3001, conductor 520, through contacts of the switch 600, to ground on conductor 503. This circuit provides a test to ascertain whether the office frame has completed the connection. Relay 2450 locks through its right front contact and operates the relays 2407 and 2408. These relays bring about the release of the office frame trunk connector 3000 and the office trunk connector 3001, whereby the marker is dis-

operates the relay 1605 in the sender notifying the sender that the connection has been completed and that the time is ready for releasing. This circuit may be traced from ground, over conductor 2520, through the left front contact of relay 2402, left front contact of relay 2407, thence over conductor 2439, as previously traced through the winding of relay 1605 to battery. The sender thereupon brings about the release of the sender-connector 2200 and the outgoing marker is disassociated from the sender and restored to common use.

15 The vertical magnets 609 and 611 of the office switch are released and the connection therethrough is maintained by the continued energization of the horizontal magnet 615.

Transfer of class information from the outgoing marker to the sender.—Before the marker is disconnected from the sender as above noted on an interoffice call of this particular class, certain class information is transmitted from the marker and recorded in the sender in order that the sender may properly govern the succeeding operations in further extending and completing the call.

20 It may be assumed that the called office is one equipped with relay call indicator equipment designed to receive codes of impulses from the sender in the local mechanical office for the purpose of selecting and operating indicating elements before an operator's position to select the number of the wanted line.

25 At the time the routing relay 2808 in the marker operates, it causes the operation of the class relay 1610 in the sender. The circuit for this purpose may be traced from battery, through the winding of said relay, conductor 1611, through the frame connector 2200, thence over conductor 2523, contact of relay 2808 to ground. The class relay 1610

30 indicates to the sender that the call which is being extended is one to a distant office equipped with the call indicator. It will also be recalled that the wanted line in this instance does not have a party letter suffixed. Accordingly, this information is also given the sender in order that it may omit to transmit impulses representing the stations digit. For this purpose, the skip stations relay 1604 is operated in the sender during

35 the time the sender is connected to the outgoing marker. The circuit for this purpose may be traced from battery, through the right winding of relay 1604, conductor 1612, right back contact of relay 2009, conductor 1815, conductor 1942, through the connector 2200, to ground at the left contact of relay 2808. Relay 1610 locks through its right contact, through the inner right back contact of relay 1613, conductor 1519 to ground.

40 *Transmission of code impulses to the dis-*

tant office.—The sender has received the necessary information regarding the type of connection that is being extended and now prepares to transmit codes of impulses representing the numerical designation of the wanted line over the trunk circuit to the distant call indicator office.

The call indicator equipment at the distant office is designed to receive codes of impulses made up of positive and negative impulses of weak and strong character which represent the various digits of the numerical designation. The equipment illustrated in Fig. 14 serves to create and transmit these impulses over the conductors 1230 and 1231 thence to the tip and ring of the trunk outgoing to the distant office. For a general understanding of the manner in which code impulses are grouped and transmitted, reference is made to the patent to S. B. Williams, No. 1,517,331, issued Dec. 2, 1924. Inasmuch as the impulse generating equipment does not constitute the invention being claimed in this case, it is not considered necessary to go into a detailed description of the manner in which it operates.

At the time the relay 1604 operates, it closed a circuit for the start relay 1401 which may be traced from battery, through the left winding of said relay, outer left contact of relay 1402, conductor 1403, contact of relay 1404, conductor 1405, left contact of relay 1610, outer left contact of relay 1614, conductor 1606, right contact of relay 2007, conductor 2008, to ground as previously traced. Relay 1401 bridges the relay 1406 across the trunk leading to the distant office. This relay operates and operates relay 1407 which in turn operates relay 1408. Relay 1408 locks. When relay 1406 again releases, relay 1407 deenergizes and relay 1409 is thereupon operated. Relay 1409 operates relay 1410 which starts the impulse generating relays in operation. These relays complete cycles and transmit impulses over the tip and ring conductors of the trunk.

The impulse generating mechanism shown in Fig. 14 is associated with the numerical stations registers, Fig. 21, by means of the switching relays 2010 shown in Fig. 20. When all the impulses involved have been transmitted, relay 1404 operates in a circuit from battery, through its windings, thence through contacts of relays 1411 and 1412, conductor 1413, through the inner left contact of relay 2011, to ground at the contact of relay 2012. Relay 1404 operates the sender release relay 1524 by means of a circuit from battery, through the winding of relay 1524, left contact of relay 1514, conductor 1525, back contact of relay 1414, outer right front contact of relay 1404, conductor 1415, outer left contact of relay 1527,

to the grounded conductor 1519. Relay 1524 causes the release of the sender as hereinbefore described.

Establishment of connection to an operator's position.

In case a calling subscriber wishes to obtain connection with an operator, he may do so by dialing a special code. Also, connections which are attempted to vacant lines, 75 connections which encounter trouble, connections attempted to restricted zones, etc., are also routed to the operators' positions for attention.

If a subscriber wishes to communicate with the operator, he dials the digit zero, which results in the transmission of 10 impulses. From inspection, it will be found that at the end of a series of 10 impulses, the counting relays 1913, 1905, 1932 and 1931 are operated. With these relays energized, the relay 1816 is operated in a circuit from battery through the winding thereof, inner right back contact of relay 1805, thence through the left front contact of relay 1932, outer right front contact of relay 1904, thence to the grounded conductor 1812. Relay 1816 operates and locks through conductor 1812.

It will also be found from inspection that with these particular counting relays energized, none of the register relays are operated. The marker is immediately associated with the sender by operating the relay 1509. The circuit for this relay may be traced from battery, through its winding, thence as previously traced through conductor 1518, thence through the outer right contact of relay 1810, left back contact of relay 1801 which has become released, to ground on conductor 1812. As previously described in full, the relay 1509 causes the connection of an idle marker to the sender, following which the register relays 2500, 2501, and 2502 in the marker are operated. Since none of the register relays of the sender are operated, the marker register relays all release when relay 2711 becomes energized.

The routing relay 2801 which indicates an operator's call is operated next in a circuit from battery, through the winding of said relay, conductor 2824, through the outer right normal contact of relay 2503, inner left normal contact of relay 2504, right back contact of relays 2505 and 2506 to the grounded conductor 2517. Relay 2801 determines the operation of the outgoing marker in such a manner that the district selector switch 400 is selectively operated to choose a trunk leading to an operator's position. The details of the functioning of the marker correspond with those in connection with other calls previously traced and will not be given in this connection.

Since this is an operator's call, the repeat-

ing coil 302 will not be required inasmuch as talking battery supply is usually furnished from an operator's cord circuit. Therefore, while the marker is associated with the 5 district selector, the relay 301 is operated in a circuit from battery, through the upper winding of said relay, conductor 321, contact of magnet 410, conductor 427, through the frame connector 2900, thence over conductor 10 2933, through the left contact of relay 2801 to ground. Relay 301 disconnects the tip and ring conductors from repeating coil 302 and opens the holding circuit of relay 305.

When the sender is disconnected from the 15 trunk 216, relays 300 and 306 and 305 become deenergized. Relay 306 being slow-to-release does not retract its armatures to remove ground from the sleeve conductor of the trunk until a trunk relay at the operator's 20 position has had an opportunity to operate and supply a substitute holding ground in the well known manner.

When the operator removes her plug and the called subscriber hangs up his receiver, 25 the connection is restored and the district selector switch 400 releases.

Time measure controls and other details.

Operation of the sender time measure equipment.—The mechanism shown in Fig. 30 17 governs the sender in such a manner that in the event of trouble, wherein the sender does not progress in its normal sequence of operations, the presence of such condition 35 may be called to the attention of the operators or attendants and the sender itself automatically released. Furthermore, the calling subscriber may partly dial the number and then abandon the call without hanging up the receiver. This gives rise to what 40 is known as an unfinished dialing condition and the sender would be held up indefinitely if some means were not provided for automatically releasing the same at the end of 45 a definite interval of time.

Again, the calling subscriber's line may be closed either due to some abnormal condition on the line or because of the fact that he has removed his receiver and abandoned 50 the telephone instrument indefinitely whereupon a sender is automatically seized and would otherwise be held busy for an unwarranted time were it not for the time measuring equipment.

55 This condition is known as a permanent signal.

Again, the sender having been taken into use may, due to its own fault, fail to operate regularly, in which case what is known 60 as a stuck sender condition prevails. Also other conditions may arise in which it becomes desirable to release the sender after a definite interval has expired. To this end, the time measuring device comprises a series 65 of pairs of counting relays 1700 which are

operated in succession by means of a slow moving constantly driven interrupter 1711. By arbitrarily connecting in any desired number of these pairs of counting relays at the distributing frame 1713, the duration of 70 the time interval may be varied at will.

In order to illustrate the functioning of the time measuring device, it will be assumed a permanent signal condition arises on the calling subscriber's line. The closure 75 of the tip and ring conductors causes the operation of a line switch, a sender selector switch, and the association of an idle sender all in the manner hereinbefore described. When the relay 1504 operates, it operates the 80 relay 1704 in a circuit from battery, through the right winding of the latter relay, conductor 1714, inner left back contact of relay 1802, to ground over conductor 1812. Relay 1704 operates the relay 1701 in a circuit from 85 battery, through the left winding of the latter relay, inner right contact of relay 1704, to ground over conductor 1714. Relay 1701 starts the counting relays 1700 in 90 operation. Relay 1707 is first operated in a circuit from battery, through its winding, right back contact of relay 1708, conductor 1715, left contact of relay 1703, inner contact of relay 1701, outer left back contact of relay 1702, conductor 1716, contact of the 95 interrupter 1711 to ground. Relay 1707 operates and closes a holding circuit, through its winding and the left winding of relay 1708, right contact of relay 1707, right back contact of relay 1709, right back contact of relay 1717, to ground at the outer contact of relay 1701. Relay 1708 being shunted is not operated. When interrupter 1711 opens its contact, the shunt is removed 100 and relay 1708 operates in series with relay 1707. On the next closure of the interrupter, ground is extended over conductor 1715, through the right front contact of relay 1708, right back contact of relay 1710, winding of relay 1709 to battery. Relay 110 1709 operates and prepares a holding circuit for itself in series with the left winding of relay 1710. The latter relay being shunted, however, does not operate. Relay 1709 releases the relay 1707 but relay 1708 remains 115 locked through its right winding and contact to the grounded conductor 1715. When the interrupter 1711 opens, relay 1708 releases and relay 1710 operates in series with relay 1709.

Relay 1703 is now operated to indicate that the required time interval has been measured. The circuit for this relay may be traced from battery, through its winding, outer left contact of relay 1704, through the 125 distributing frame 1713, inner left contact of relay 1710, thence to ground at the outer contact of relay 1701. Relay 1703 prevents the further operation of the counting relays and operates the permanent signal relay 130

1521. The circuit for this latter relay may be traced from battery, through the winding thereof, conductor 1529, outer right contact of relay 1703 to ground at the outer 5 right contact of relay 1704. The relay 1521 operates relay 1509 which as hereinbefore explained, causes the sender to become associated with an idle outgoing marker.

Upon the association of the outgoing 10 marker with the sender, the routing relay 2800 in said marker, which represents the permanent signal condition, is operated. The circuit for this relay may be traced from battery, through the winding thereof, 15 conductor 2825, through the sender-connector 2200, conductor 2219, right front contact of relay 1521, thence over conductor 1936 as hereinbefore traced to ground through the right contact of relay 2711 in 20 the marker. The relay 2800 serves in the manner hereinbefore explained in connection with the other routing relays to cause the marker to control the district selector switch 400 in such a manner as to select a 25 trunk leading to an operator's position. In this way, the operator is placed in communication with the calling line.

Relay 1703 also closes a circuit for flickering lamp 1530 at a monitoring operator's 30 position. This circuit may be traced from battery, through the lamp, outer contact of relay 1510, thence over conductor 1531, middle right contact of relay 1703, through the contact of the fast interrupter 1712 to 35 ground.

The release of the equipment may take place in the manner fully described hereinbefore.

Operation of the marker time measuring devices.—The incoming and outgoing markers are also equipped with time measuring devices which measure an interval of time which is ordinarily sufficient for the markers to complete their functions. In case of 45 trouble, however, the time measure device has sufficient time in which to complete the measurement of the interval and in so doing, gives signals to the attendants and also causes an automatic signal to be given to 50 the calling subscriber.

Referring to the measuring device for the outgoing marker shown in Fig. 26, a set of counting relays 2602 similar in purpose and operation to the counting relays of the 55 sender measuring device is employed for measuring the time allotted for the marker to complete its operations. When the marker is first seized, and relay 2708 operates, a circuit is completed for energizing relay 60 2605. This circuit may be traced from battery, through the right winding of relay 2605, conductor 2607, right back contact of relay 2404 to ground over conductor 2520. Relay 2605 operates relay 2603 in a circuit 65 through the left winding of the latter relay,

inner right contact of relay 2605 to ground on conductor 2607. Relay 2603 starts the counting relays 2602 in operation under the control of the interrupter 2607. At each opening and closing of the interrupter, a 70 pair of counting relays is operated.

If the marker completes its functioning in the usual course, relay 2404 operates and opens the circuits of relays 2605 and 2603 before the measuring device has had sufficient 75 time to complete its period. On the other hand, if the marker encounters difficulty and relay 2404 does not operate in the ordinary course, the relay 2604 receives energizing current after the proper number of counting 80 relays have been operated. The circuit for relay 2604 may be traced from battery, through its left winding, middle left contact of relay 2605, thence through the distributing frame 2608, inner left contact of 85 relay 2609 to ground at the outer contact of relay 2603. Relay 2604 operates the relay 2600. Relay 2604 locks through its right winding and contact of keys 2610 and 2611 to ground. Relay 2600 lights the lamp 2612 to notify the attendant that the marker is in trouble. Relay 2604 at its outer right contact also closes a circuit for operating relay 2452.

Relay 2452 at its outer left contact, closes 90 a circuit from ground over conductor 2453 through the sender connector 2200, conductor 2220, winding of relay 1517 to battery. The relay 1517 in the sender locks to the 95 grounded conductor 1519, and at its inner left contact connects the tone apparatus 1532 to the left hand winding of the balancing coil 1501. A tone current is induced 100 in the right winding of the balancing coil and transmitted over the calling subscriber's line to give him a signal which is recognized as indicating that the present connection cannot be further extended and that a 105 new trial should be made.

The attendant may take such action as is 110 necessary to ascertain the condition in the marker.

The incoming markers are also equipped with a similar time measuring device, one of which is illustrated in Fig. 35. The purposes 115 of this mechanism are ordinarily the same as those already described in detail and it is not believed that a further discussion is necessary.

Class of service equipment in the sender.— 120 As has been explained from time to time hereinbefore, the senders are provided with a number of class-of-service relays illustrated in Fig. 16. These relays are operated from the marker after the latter has received the office code and has ascertained therefrom the nature of the connection that is required. Circuits for the various relays shown in Fig. 125 16 are shown through the sender connector 2200 to the distributing frame 2813 in the 130

marker, whence they are connected as desired to the contacts of the routing relays. For simplicity in the disclosure, the leads extending from several of these relays through the sender-connector 2200 to the marker have been omitted and are illustrated in conventional manner by means of brackets and a single line.

What is claimed is:

- 10 1. The combination in a telephone system of selective switches, means for extending connections to said switches, a number of recording senders, a number of equivalent controlling mechanisms, each associable with any sender and with any switch for controlling the selective operation of such switch, and means separate from the extended connection for connecting simultaneously, a plurality of controlling mechanisms with respective senders and with respective switches.

25 2. The combination with telephone lines and selective switches of means to extend said lines to said switches, a number of senders for recording designations sent over the lines, a number of equivalent markers associable with said senders and with said switches for controlling the latter, and means separate from the extended connection for connecting simultaneously a plurality of markers with respective senders and with respective switches.

30 3. The combination with telephone lines and selective switches of means to extend said lines to said switches, a number of senders for recording the designations of wanted lines sent over a calling telephone line, a number of equivalent markers associable with said senders and with said switches, means to transfer the recorded designations from the senders to the markers to selectively operate the switches, and means separate from the extended connection for connecting simultaneously a plurality of markers each with a different sender and each to a different switch.

35 4. The combination with selective switches arranged in groups of means for extending connections to said switches, a number of recording senders, a number of equivalent markers, each associable with any sender and with any switch, means separate from the extended connections for simultaneously connecting a plurality of markers with respective senders, and means for connecting simultaneously a plurality of markers each to any switch in each of said groups.

50 5. The combination with selective switches divided in groups of means for extending telephone connections to said switches, designations recording senders, a number of equivalent markers, each connectible with any sender and with any switch, means separate from the extended connection and including a multi-contact relay device for con-

nected simultaneously a plurality of markers with respective senders, and a multi-contact relay device for connecting simultaneously a plurality of markers each to any switch in each of said groups.

55 6. The combination with a plurality of selective switches at a switching stage of means for extending connections to said switches, a number of recording senders common to all of said switches, a number of equivalent controlling markers for the switches at said stage, each marker associable with any sender and with any switch for controlling such switch, and means for connecting simultaneously a plurality of markers with respective senders and with respective switches.

60 7. The combination with a plurality of selective switches at a switching stage of means for extending connections to said switches, a number of recording senders common to all of said switches, a number of equivalent controlling markers for the switches at said stage, each marker associable with any sender and with any switch for controlling such switch, means for connecting simultaneously a plurality of controlling markers with different senders and with different switches, and means in each marker to select a group of trunks, to select an idle trunk in the group and to operate the switch to extend the connection to such idle trunk.

65 8. The combination with telephone lines and selective switches of means to extend said lines to said switches, groups of trunks outgoing from each of said switches, a number of recording senders, a number of markers, each associable with any sender, means for connecting a plurality of markers simultaneously with respective senders, means for connecting a plurality of markers simultaneously with respective switches, means for connecting each marker so connected to a selective switch with any group of trunks outgoing therefrom, and means in said markers for testing said trunks and selectively operating the switches to extend the telephone lines over said trunks.

70 9. In a telephone system, selective switches at a switching stage, other switches at a second stage, means for extending connections to said first switches, recording senders, controlling markers, each associable with any sender and with any switch at either stage, means separate from the extended connections for connecting simultaneously a plurality of markers with respective senders and with respective switches at the first stage for selectively operating said latter switches to further extend connections to the second stage, and means for thereupon connecting simultaneously the markers with respective switches at said second stage.

10. In a telephone system, selective switches at a switching stage, other switches at a second stage, means for extending connections to said first switches, recording senders, controlling markers, each connectible with any sender and with any switch at either stage, trunks inter-connecting the switches of the first and second stages, means separate from the extended connections for connecting simultaneously a plurality of markers with respective senders and with respective switches at the first stage for selectively operating said latter switches to further extend the connections over said trunks to the second stage, trunks outgoing from the switch at the second stage, and means for connecting simultaneously the markers with the respective switches at the second stage for selectively operating the same to further extend the connections over said outgoing trunks.

11. In a telephone system, a plurality of recording senders, a plurality of switch controlling markers, a connecting device comprising a number of sections for connecting said senders to any of said markers, said senders arranged in groups and each group appearing in a different section, each marker appearing in all sections, and means for controlling the operation of said connecting device to connect simultaneously a plurality of senders to respective markers.

12. In a telephone system, a plurality of recording senders, a plurality of switch controlling markers, a connecting device comprising a number of sections for connecting said senders to any of said markers, said senders arranged in groups and each group appearing in a different section, each marker appearing in all sections, and means for controlling said connecting device to permit one sender in each group to connect to a marker through the corresponding sections simultaneously.

13. In a telephone system, a plurality of recording senders, a plurality of switch controlling markers, a connecting device comprising a number of sections for connecting said senders to any of said markers, said senders arranged in groups and each group appearing in a different section, each marker appearing in all sections, means for controlling the operation of said connecting device to permit one sender in each group to connect to a marker through the corresponding sections simultaneously, and means to prevent the connection of a second sender in any section with the marker.

14. In a telephone system, a plurality of recording senders, a plurality of switch controlling markers, a connecting device comprising a number of sections for connecting said senders to any of said markers, said senders arranged in groups and each group appearing in a different section, operating

means for giving each of the senders in each section a first choice to a different marker and subsequent choices to other markers, and means for controlling the operation of the connecting device to connect simultaneously a plurality of senders to respective markers.

15. In a telephone system, a plurality of groups of lines, selective switches, means for extending connections to said switches, a switch controlling marker common to all of said lines, a number of translators, one for each group of lines, means for connecting said marker with a desired one of the translators, means for connecting the marker and translator to said switches for selectively operating the same to make connection with a desired line in the corresponding group.

16. In a telephone system, a number of groups of lines, selective switches, means for extending connections to said switches, a plurality of controlling markers common to all of said switches, a number of translators one for each group of lines, means for connecting any one of said markers with a desired one of the translators, means for connecting the marker and translator to said switches for selectively operating the same to make connection with a desired line in the corresponding group.

17. In a telephone system, groups of lines, a selective switch for each group, trunks leading to said switches, means for extending connections over said trunks to said switches, a plurality of switch controlling markers common to all of said lines, a number of translators, one for each group of lines, means to connect a marker to the translator which controls the switch having access to the called line, means in the marker for testing and selecting a trunk leading to the proper switch, and means to connect the marker and associated translator to such switch for operating the same to select the called line.

18. In a telephone system, a switch having a plurality of link circuits, a second switch also having a plurality of link circuits, a group of trunks interconnecting said switches and having access to links in each switch, and means separate from said switches for testing the links and trunks to ascertain the simultaneous idle condition of a trunk, a link in the first switch to which such trunk has access and a link in the second switch to which such trunk has access.

19. In a telephone system, a group of switches each having link circuits, a second group of switches each having link circuits, a group of trunks interconnecting said switches and having access to links in switches of each group, and a common testing means for testing the links and trunks

- to ascertain the simultaneous idle condition of a trunk, a link in a switch of the first group to which such trunk has access and a link in a switch of the second group to which said trunk has access.
20. In a telephone system, a group of switches each having links, a second group of switches each having links, a plurality of groups of trunks interconnecting each switch of the first group with the switches of the second group, and means common to all of said switches for testing the links and trunks to determine the simultaneous idle condition of a trunk, a link in a switch of the first group to which said trunk has access and a link in a switch of a second group to which said trunk has access.
21. In a telephone system, a group of switches each having links, a second group of switches each having links, a plurality of groups of trunks interconnecting each switch of the first group with switches of the second group, and a series of testing relays common to switches and groups of trunks and associative with any switch of the first group, with any group of trunks outgoing therefrom and with any switch of the second group in which such trunks appear for testing the same to determine the simultaneous idle condition of a trunk, a link in a switch of the first group to which such trunk has access, and a link in a switch of the second group to which such trunk has access.
22. In a telephone system, a switch having a plurality of link circuits, a second switch also having a plurality of link circuits, a number of trunks interconnecting said switches, each trunk having access to a portion only of the links in the first switch, each trunk having access to a portion only of the links in the second switch, and means separate from the switches for testing the links and trunks to determine the simultaneous idle condition of a trunk, a link in the first switch to which such trunk has access and a link in the second switch to which such trunk has access.
23. In a telephone system, a switch having a group of links, a second switch having a group of links, a group of trunks interconnecting said switches, each link of the group of the first switch having access to a single one of said trunks, each link of the group of said second switch having access to a plurality of said trunks, and means for testing the links and trunks to determine the idle condition simultaneously of a trunk, the link in the first switch to which such trunk has access and the link in the second switch to which such trunk has access.
24. In a telephone system, a switch having a group of links, a second switch having a group of links, a group of trunks interconnecting said switches, each link of
- the group of the first switch having access to a single one of said trunks, each link of the group of said second switch having access to a plurality of said trunks, means for testing the links and trunks to determine the idle condition simultaneously of a trunk, the link in the first switch to which such trunk has access and the link in the second switch to which such trunk has access, means for rendering non-selectable the trunk to which any link of the first switch has access when such link is busy, and means for rendering non-selectable all trunks to which any link of the second switch has access when such link is busy.
25. In a telephone system, a switch having a group of links, a second switch having a group of links, a group of interconnecting trunks, each link of the group of the first switch having access to a single one of said trunks, each link of the group of the second switch having access to a plurality of said trunks, a set of testing relays associative with said switches for testing said links and trunks, and means including said relays for rendering a trunk non-selectable when the link in the first switch having access thereto is busy and for rendering non-selectable all of said trunks to which a link in the second switch has access when said latter link is busy.
26. In a telephone system, a switch having vertical rows of contacts and link circuits, a second switch also having vertical rows of contacts and link circuits, a group of interconnecting trunks occupying a single row of contacts in the first switch and a plurality of rows in the second switch, operating magnets for each row of contacts for causing the connection of the links to the trunks, testing means for determining a simultaneous idle condition of a link in the first switch, a trunk having access to said link, and a link in the second switch having access to said trunk, and means determined by the test for selecting and operating the proper magnet.
27. In a telephone system, a group of selector switches, trunks leading to said switches, a plurality of controlling markers for controlling the selective operation of said switches to extend connections, a connector for connecting any one of said markers to any one of said switches, and means controlled by a marker through said connector for altering the condition of one of said trunks when the connection being extended is of a particular class.
28. In a telephone system, a group of selector switches, trunks leading to said switches, a plurality of controlling markers for controlling the selective operation of said switches to extend connections, a connector for connecting any one of said markers to any one of said switches, and means

controlled by a marker through said connector for changing the talking characteristics of one of said trunks when the connection being extended is of a particular class.

5 29. In a telephone system, a group of selective switches, means for extending connections to said switches, a switch controlling marker, a connector operable to connect the marker to the particular switch to 10 which a connection has been extended, a group of trunks outgoing from said switches, said group being divided in subgroups and each subgroup appearing only in a portion of said switches, a trunk connector 15 for connecting the marker to said trunks to test the same, and means to selectively operate said trunk connector to connect the marker to the particular subgroup of trunks appearing in the switch to which the connection has been extended.

20 30. In a telephone system, a group of selective switches, means for extending connections to said switches, a plurality of markers, a connector operable to connect any one of said markers to the particular switch to which a connection has been extended, a group of trunks outgoing from said switches, said trunks being divided into subgroups and each subgroup multiplied to appear only in a portion of said switches, a trunk connector for connecting said markers to the trunks for testing the same, and means to selectively operate said trunk connector to connect a marker to the particular subgroups of trunks appearing in the switch to which the connection has been extended.

25 31. In a telephone system, a group of switch frames, means for extending connections to said frames, a plurality of switch controlling markers, a frame connector operable to connect any one of the markers to the particular switch frame to which a connection has been extended, groups of trunks outgoing from said frames, each group being divided in subgroups and each subgroup multiplied to a portion of the switch frames, a trunk connector for connecting the markers to said trunks, and means controlled by the frame connector for selectively operating said trunk connector to connect the marker to the particular subgroup of trunks appearing in the switch to which the connection has been extended.

35 32. In a telephone system, lines, a group of selective switches, a group of trunks divided into subgroups and all having the same numerical identity, said subgroups each appearing only in a portion of said switches, a marker common to all switches for controlling the same and common to all trunks for testing the same, means for extending a line to any one of said switches, means for giving the marker information as to the location of the particular switch to which the line has been extended, and

means operative in accordance with such information for connecting the marker to the subgroup of trunks appearing in said particular switch.

33. The combination with a telephone line 70 of a number of selective switches, automatic means for extending said line to one of the switches, a controlling mechanism for said switches, a connector for each switch, each connector arranged for operation for connecting said mechanism to the corresponding switch, means in the controlling mechanism operated differently when the line is extended to different ones of said switches, means responsive to said last means for selecting one of said connectors to be operated, and means controlled by said mechanism for selectively operating the switch to which it is connected.

34. The combination with a telephone line 85 of a number of groups of selective switches, means for extending said line to any one of said switches, a controlling mechanism for said switches, an automatic switch for connecting the extended line with a portion of 90 said controlling mechanism, a connecting device for each group of selective switches, each device arranged to connect a portion of said mechanism to any one of the switches in the corresponding group, means for selecting the particular device to be operated, and means governed by said mechanism for selectively operating the selective switch to which it is connected.

35. In combination, a calling subscriber's line, a plurality of groups of selective switches, means for extending said line to one of said switches, a register and controlling mechanism for controlling said switches, means for associating the extended line with said controlling mechanism, a connecting device for each group of switches, each device arranged to connect the mechanism to any one of the switches in the corresponding group, means for selecting the 100 particular connecting device which has access to the group to which said line has been extended, means for operating the selected device to connect said mechanism to the particular switch in the group to which 105 said line has been extended, and means controlled by said mechanism for selectively operating such switch.

36. The combination with a telephone line 120 of a number of groups of selective switches, automatic means for extending said line to any one of said switches, a registering and controlling mechanism for controlling said switches, means for associating the extended line with said mechanism, a connector for each group of switches, each connector arranged to connect said mechanism to any one of the switches in the corresponding group, means for selecting one of said connectors for operation, means controlled 125 130

jointly by the controlling mechanism and by the particular switch to which the line is extended for operating the selected connector to connect said mechanism to said particular switch, and means controlled by said mechanism for selectively operating said particular switch.

37. In combination, a telephone line, a number of selective switches, means for extending said line to one of said switches, a number of register senders, a sender selector switch for connecting the extended line to one of said senders, a marker common to said switches, a connecting device for each switch, each device arranged for operation independently of the condition of the other devices for connecting said marker to the corresponding switch, means for selecting the particular one of said connecting devices to be operated, means for associating said senders with the marker, and means controlled by said marker for selectively operating the switch to which it is connected.

38. In combination, a telephone line, a number of selective switches, means for extending said lines to one of said switches, a register sender mechanism, means for extending said line to said sender, a plurality of markers common to said selective switches and associative with said sender, a connector for each switch, each connector arranged to connect any one of said markers to the corresponding switch, means for selecting a particular one of said connectors to be operated for the purpose of connecting one of said markers to the corresponding switch, and means controlled by the connected marker for selectively operating the switch to which it is connected.

39. In combination, a plurality of groups of selective switches, senders, a number of switch controlling markers, means for connecting simultaneously a plurality of said markers each with a different sender, connectors, one for each group of switches, and means for selectively operating said connectors to connect simultaneously the markers which are connected to senders to switches of said groups.

40. In combination, lines, a number of groups of selective switches, means for extending simultaneously lines to a plurality of said groups of switches, recording senders, a number of switch controlling markers, means for connecting simultaneously a plurality of said markers each with a different sender, connectors, and means for selectively operating said connectors to connect simultaneously the markers which are thus connected to senders each to a different one of the particular switches to which said lines have been extended.

41. The combination with subscribers' lines of a number of selective switches,

means for extending one of said lines to any switch, senders for recording designations, markers for controlling said switches, connecting means for connecting said markers to said switches, means for associating a sender with the extended line, means for associating such sender with any one of said markers, means for giving to the associated marker information as to the location of the particular switch to which said line has been extended, and means for selectively operating said connecting means in accordance with said information to connect said associated marker with such switch.

42. The combination with a plurality of selective switches, of a controlling mechanism associative with any one of said switches for controlling the selective operation of the same, a release circuit leading through contacts of the switch with which said mechanism is associated, release means responsive to the closure of said circuit at the contacts of said switch, and means controlled by said release means for releasing said mechanism.

43. The combination with a plurality of selective switches each having contacts for extending connections, of a controlling marker common to all of said switches and associative with any one thereof for controlling its selective operation, and means rendered effective by the closure of the contacts of said switch immediately upon the operation of said switch for causing the release of said marker.

44. The combination with a plurality of selective switches each having contacts for extending connections, of a controlling marker common to all switches, means for connecting said marker to any one of said switches for controlling the selective operation thereof, means responsive to the closure of the contacts of said switch as soon as said switch is operated for causing the release of said marker, and means for causing the release of said marker in case the switch fails to operate.

45. The combination with a plurality of selective switches each having contacts for extending connection, of a controlling marker common to said switches, means for connecting said marker to any switch for controlling the operation thereof, means rendered effective upon taking a marker into use for counting a definite interval of time, means for causing the release of said marker upon the expiration of said time interval, and means rendered effective by the closure of the contacts of the switch to which the marker is connected for causing the release of said marker.

In witness whereof, I hereunto subscribe my name this 27th day of March A. D., 1924.

WARREN W. CARPENTER.
